UNITED STATES PATENT OFFICE

2,302,715

WINDING MACHINE

Charles D. Reynolds, Gustaf S. Beckman, and
Herman A. Moe, Cranston, R. I., assignors to
Universal Winding Company, Boston, Mass., a
corporation of Massachusetts

Application March 26, 1941, Serial No. 385,346

60 Claims. (Cl. 242—32)

The present invention relates to improvements in automatic winding machines of the type illustrated and described in the application for United States Letters Patent of Charles D. Reynolds et al., Serial No. 231,044, filed September 21, 1938, now Patent No. 2,257,657. More particularly the present invention relates to winding machines for winding cops, bobbins, pirns and other forms of textile packages; for example, bobbins of yarn to be used as filling or 10 weft in the shuttles of looms.

In the present specification and claims the terms "bobbin" and "wound yarn-carrier" are employed for convenience of description to apply to any usual form of textile package and the term "yarn" is intended to designate all types of strand material.

A particular object of the invention is to provide a machine of the type indicated which is entirely automatic in operation, requiring no attention on the part of the operator during its normal operation except to replenish the supplies of yarn and fill the magazines with empty yarn-carriers or bobbins.

Another object of the invention is to provide a machine of the type indicated in which the various elements of the machine are either operated or controlled by electromagnets.

Another object is to provide a central controller or multiple switch for controlling the energization of the electromagnets in predetermined sequence to doff a wound bobbin, don an empty bobbin and start the winding operation.

Another object is to provide a machine of the type indicated in which the operation of the controller is initiated by the growth of the winding on the bobbin.

Another object is to provide a machine of the type indicated with longitudinally spaced spindles for rotatably mounting a bobbin therebetween.

Another object of the invention is to provide a machine of the type indicated with an electromagnet for withdrawing one of the spindles to doff a wound bobbin.

Another object is to provide a machine of the type indicated with a screw-threaded traverse rod along which the thread-guide advances during winding and means for rotating the traverse rod to return the thread-guide to initial position.

Another object is to provide a machine of the type indicated with an electromagnet-operated clutch for connecting a drive shaft to rotate the threaded traverse rod.

Another object is to provide means for traversing the yarn rearwardly of the completed bobbin during its rotation to form a "back wind" on the bobbin.

5 Another object is to provide a machine of the type indicated with a yarn-retriever adapted to traverse the yarn rearwardly of the bobbin to form the back wind thereon and thereafter position the yarn strand to be attached to an empty bobbin.

Another object is to provide a yarn-retriever of the type indicated for traversing the yarn rearwardly, positioning the yarn to adapt it to be attached to an empty bobbin and thereafter restrain the yarn to wind a "bunch" on the empty bobbin prior to the service winding.

Another object is to provide a machine of the type indicated with electromagnet-operated detents for controlling the relative positions of the yarn-retriever.

Another object is to provide a machine of the type indicated with a bobbin-transferring cradle adapted to be moved into position to don an empty bobbin and thereafter withdrawn to bobbin-receiving position by an electromagnet.

Another object is to provide a machine of the type indicated with an electromagnet-operated detent for retaining the bobbin-transferring means in its bobbin-receiving position.

Another object is to provide a machine of the type indicated with a chute having means therein for temporarily detaining a doffed bobbin adjacent the winding spindle and thereafter releasing it to carry the yarn strand into position to be attached to the empty bobbin.

Another object is to provide means of the type indicated adapted to cooperate with the yarn-retriever to position the yarn strand between the end of the spindle and the head of an empty bobbin.

Another object is to provide a yarn trap for guiding the yarn strand trailing from the wound bobbin against a knife to sever it from the bobbin.

Another object is to provide a pivoted gate in the chute and electromagnetic means for releasing the gate to discharge the wound bobbin from the chute.

Another object is to provide a machine of the type indicated in which the rotation of the winding spindle is arrested, a wound bobbin doffed and an empty bobbin donned upon completion of the winding and also having means for arresting the winding without doffing the bobbin when the yarn breaks or its supply is exhausted.

55 Another object is to provide a machine of the

type indicated having both electrical and mechanical controls for starting and stopping the winding operation.

Another object of the invention is to provide a machine of the type indicated in which a separate mechanical control is provided for automatically stopping the spindle upon failure of the electrical control means.

Further objects of the invention are set forth in the following specification which describes a preferred form of construction of the machine, by way of example, as illustrated by the accompanying drawings. In the drawings:

Fig. 1 is a transverse sectional view of the main casing of a multiple spindle winding machine incorporating the novel features of the present invention and showing a single spindle and its operating mechanism in side elevation;

Fig. 2 is a plan view of the winding spindle and its operating mechanism illustrated in Fig. 1;

Fig. 3 is a transverse sectional view on line 3—3 of Fig. 2 showing the clutch-operating means for disconnecting the spindle from its drive shaft;

Fig. 4 is an enlarged elevational view part-sectional on line 4—4 of Fig. 2 and showing the relationship of the parts during a winding operation;

Fig. 5 is a detailed plan view partly in section showing the mounting for the rearward end of the threaded traverse rod section to adapt it for rotation;

Fig. 6 is a longitudinal sectional view on line 6—6 of Fig. 5 showing the meshing engagement of the threads in the nut on the thread-guide carriage with the screw-threads on the traverse rod for advancing the thread-guide longitudinally of the bobbin during winding;

Fig. 7 is a transverse sectional view on line 7—7 of Fig. 5 showing the strap for clamping the bearing at the rearward end of the traverse rod in adjusted position;

Fig. 8 is a transverse sectional view on line 8—8 of Fig. 5 showing the coupling for connecting the separate sections of the traverse rod;

Fig. 9 is a front elevational view of a part of the machine casing showing the separate electromagnet and mechanical operating means for starting and stopping the winding operation;

Fig. 10 is a transverse sectional view on line 10—10 of Fig. 9 showing the latch for retaining the starting mechanism in operative position and the electromagnet-operated trip for the latch;

Fig. 11 is a detailed view partly in section showing the mechanical latch-trip mechanism adapted to be operated by excessive growth in the winding, or upon breakage of the yarn strand, or failure of the yarn supply to release the starting mechanism and stop the winding operation;

Fig. 12 is a view similar to Fig. 11 showing the yarn-controlled drop-wire rocked to a position between a bunter and a rockable arm of the mechanical latch-trip mechanism;

Fig. 13 is a detailed view part-sectional on line 13—13 of Fig. 12 showing the rockable arm of the mechanical latch-trip mechanism held in its upright position by a control member and the yarn-controlled drop-wire positioned between the arm and the bunter;

Fig. 14 is a transverse sectional view on line 14—14 of Fig. 11 showing the rod connected to the starting mechanism for setting the yarn-

controlled drop-wire in upright position prior to the starting of the winding operation;

Fig. 15 is an enlarged view similar to Fig. 4 indicating the manner in which the control switch is operated at the completion of the bobbin and the yarn-retriever actuated to traverse the yarn rearwardly to form a back wind on the bobbin;

Fig. 16 is a longitudinal sectional view on line 16—16 of Fig. 15 showing the construction of the retractable spindle-cup;

Fig. 17 is a transverse sectional view on line 17—17 of Fig. 15 showing the electromagnet-operated detent for limiting the rearward movement of the yarn-retriever;

Fig. 18 is a view similar to Fig. 15 showing the spindle-cup retracted, an empty bobbin in position to be donned and the yarn-retriever moved to its rearmost limit to position the yarn strand between the end of the spindle and the head of the bobbin;

Fig. 19 is a view similar to Fig. 18 showing the empty bobbin clamped between the spindle-cup and the outer stub-spindle and the yarn-retriever retained in position to cause the bunch to be wound at the rearward end of the bobbin;

Fig. 20 is a part-sectional plan view on line 20—20 of Fig. 19 showing the inclined edge of the yarn-retriever which cooperates with the thread-guide to restrict the traverse of the yarn for winding the bunch on the bobbin;

Fig. 21 is a side elevational view of the magazine and bobbin-transferring cradle showing the latter retained in its bobbin-receiving position by an electromagnet-operated detent;

Fig. 22 is a part-sectional view on line 22—22 of Fig. 21 showing the linkage for operating the bobbin-transferring cradle and the resiliently-operated fingers on the cradle for gripping the empty bobbin;

Fig. 23 is a transverse sectional view on line 23—23 of Fig. 21 showing the bobbin-transferring cradle in bobbin-receiving position with respect to the magazine;

Fig. 24 is a sectional view on line 24—24 of Fig. 21 showing the operating pin-and-slot connections between the cradle and the bobbin-restraining gates of the magazine and illustrating the lower gate raised and the upper gate lowered when the cradle is in bobbin-receiving position;

Fig. 25 is a view similar to Fig. 23 showing the cradle moved to carry an empty bobbin into position to be donned;

Fig. 26 is a view similar to Fig. 24 showing the cradle in donning position, the lower gate engaging the lowermost bobbin in the magazine and the upper gate in raised position to release the bobbins;

Fig. 27 is a detailed view of the cradle showing the manner in which the gripper fingers of the cradle are rocked on their pivot to release the bobbin during the rearward movement of the cradle;

Fig. 28 is a detailed view part-sectional on line 28—28 of Fig. 21 showing the electromagnet-operated detent for normally retaining the cradle in its bobbin-receiving position;

Fig. 29 is a detailed view showing the means for temporarily retaining a doffed bobbin in the chute below the winding spindle and illustrating the angular position of the bobbin in the chute;

Fig. 30 is a plan view of the chute showing the pivoted gate therein and the electromagnet-operating means for the gate;

Fig. 31 is a transverse sectional view on line

31—31 of Fig. 29 showing the inclined gate which retains the doffed bobbin against one side of the chute and indicating the manner in which the gate is released by its electromagnet-operating means;

Fig. 32 is an enlarged detailed sectional view on line 32—32 of Fig. 31 showing the yarn-trap in the chute for receiving the yarn strand and positioning it to be engaged by the cutter blade;

Fig. 33 is a diagrammatic view showing the method of cooperation of the yarn-receiver and yarn-trap to position the yarn strand in alignment with the spindle-cup to adapt it to be clamped by the empty bobbin;

Fig. 34 is a plan view of the controller or multiple switch and the drive shaft therefor;

Fig. 35 is a longitudinal sectional view on line 35—35 of Fig. 34 showing the controller drive shaft and the independent electromagnet-operated clutches for connecting the controller-drive shaft to the controller and the thread-guide returning means;

Fig. 36 is a transverse sectional view on line 36—36 of Fig. 34 showing the reduction gearing for driving the controller from its drive shaft and the cooperative relationship of the cams of the controller to the switches operated thereby;

Fig. 37 is a part-sectional view on line 37—37 of Fig. 34 showing the series of switches operated by the cams of the controller;

Fig. 38 is a sectional view on line 38—38 of Fig. 37 showing the manner of mounting the switches of the controller;

Fig. 39 is a sectional view on line 39—39 of Fig. 35 showing the means for driving the threaded traverse rod from the controller-drive shaft;

Fig. 40 is a diagrammatic view of the electric circuit for the various electromagnets and the controller-operated switches for each branch of the circuit; and

Fig. 41 is a diagrammatic view of the operating cams of the controller illustrated in progressively larger proportion from one end to the other to show the relative positions of the different lobes for operating the various switches to energize the electromagnets in timed sequence.

General organization

The present invention relates in general to an automatic winding machine for simultaneously winding a plurality of bobbins. In the embodiment of the invention described and illustrated herein only a single spindle is shown with an individual control therefor. It will be understood, however, that the parts may be so arranged that each control will govern a plurality of spindles or, if desired, one control may govern all the spindles of the machine. The yarn is traversed back and forth on the rotating bobbin by means of a thread-guide mounted on a reciprocating threaded traverse rod and the guide is progressively advanced along the traverse rod during the winding to lay the yarn in overlapping layers to produce a filling-wound bobbin or shuttle cop. The rotation of the spindle and reciprocation of the thread-guide are controlled by clutches for connecting the spindle and guide to their respective drive shafts and the clutches are simultaneously operated to start or stop the winding operation.

Upon completion of the winding of a bobbin the machine operates automatically to traverse the yarn rearwardly to form a back wind on the bobbin and thereafter to doff the wound carrier, don an empty carrier and return the thread-

guide to first position to adapt it to start a new bobbin. The yarn strand is traversed rearwardly to form the back wind by a yarn-retriever which is adapted to perform the several additional functions of positioning the strand to adapt it to be attached to an empty bobbin, and after a new winding has been started, to restrict the traverse of the yarn to cause a bunch to be wound at the base end of the empty bobbin. After the yarn-retriever has been moved rearwardly to form the back wind the spindle and thread-guide are disconnected from their drive shafts to arrest the winding operation.

Immediately after the winding operation is stopped the spindle-cup is retracted to doff the wound bobbin which falls by gravity into a chute positioned therebelow and the bobbin is temporarily detained in the chute by a pivoted gate. The yarn-retriever moves rearwardly simultaneously with the retraction of the spindle-cup and the pivoted gate releases the wound bobbin to cause it to drop to tension its trailing strand between the yarn-retriever and a yarn-trap in the chute whereby to align the strand with the end of the spindle. After the wound bobbin has been doffed the threaded traverse rod is rotated to cause the thread-guide to move rearwardly to its initial position to adapt it to start a new bobbin. A cradle transfers an empty carrier from the magazine into position to be donned on the spindle and the spindle-cup is then released to cause it to engage the head or butt of the empty bobbin and clamp the yarn strand thereagainst.

Following the donning of an empty bobbin the winding spindle and thread-guide traversing means are clutched to their respective driving shafts to start winding a fresh bobbin and the rotation of the latter causes the yarn strand to be severed between the doffed bobbin and the spindle while the yarn-retriever moves outwardly to a position where it restricts the traverse of the yarn to cause a bunch to be wound. Following the winding of the bunch the cradle and yarn-retriever are moved to their initial positions and the thread-guide commences the service winding.

The various parts of the machine for doffing a wound bobbin, donning an empty bobbin and actuating the parts to start a new winding operation are either operated or their operation initiated by electromagnets and the series of electromagnets are energized in timed sequence by a central controller. The operation of the controller is initiated by an electromagnet-actuated clutch for connecting it to its drive shaft and the energization of the electromagnet is controlled by the longitudinal growth of the winding bobbin. After the controller is clutched to its drive shaft it first operates to energize an auxiliary branch circuit including the electromagnet for actuating the controller-clutch whereby to maintain the clutch engaged while the controller energizes the electromagnets for doffing a wound bobbin and donning an empty bobbin in timed sequence.

In the embodiment of the invention illustrated herein an electromagnet-operated tension-device is provided which is governed by the controller to release the tension when the yarn-retriever is operated to form the back wind on a completed bobbin and again when the winding of a new bobbin is commenced. The invention also includes mechanical control means which are automatically operable upon failure of the electromagnet control means or upon breakage or ex-

haustion of the yarn supply to stop the winding operation without operating the doffing and donning means.

Winding spindle and drive therefor

Referring to Figs. 1 and 2 of the drawings, the winding units of the machine are carried by a horizontal bed 2 usually supported from the floor by legs or standards, not herein shown. Although a single winding unit only is shown in the drawings it will be understood that a series of such units may be arranged at intervals along the machine. Mounted upon the bed 2 is a trough-like casing 3 in which the various driving elements of the winding units are enclosed. Journaled in bearings in the opposite end walls of the casing 3 are a spindle-drive shaft 4 and a traverse-drive shaft 5 and journaled in brackets 9 bolted to the back wall of the casing 3 is a controller-drive shaft 6, these three horizontal drive shafts extending longitudinally of the machine to operate the winding and control mechanisms of the various units. The spindle-drive shaft 4 and controller-drive shaft 6 may be driven from a suitable prime mover, such as an electric motor, not herein shown, by means of belts 7 and 8 and the spindle-drive shaft and traverse-drive shaft 5 are connected by suitable gearing, not herein shown. Thus, the three drive shafts 4, 5 and 6 are continuously rotated when the driving motor 30

A winding spindle 10 is journaled in a suitable bearing in the front wall of the casing 3 and extends transversely of the spindle-drive shaft 4 in the casing. The spindle 10 is driven from the drive shaft 4 by intermeshing helical gears 11 and 12 and a clutch 13 splined to the spindle and engageable with the gear 12. The clutch 13 may be of any suitable construction and as herein illustrated is of a type adapted to be held in clutching engagement with the helical gear 12. The clutch 13 is provided with a beveled flange 14 for engagement by an operating lever 15 to slide it out of clutching engagement with the gear 12, see Figs. 1 and 3. The operating lever 15 is rockably mounted at its lower end on a bracket 16 fastened in the casing 3 to adapt it for movement in a plane at right-angles to the axis of the spindle 10. A bifurcated strap 19 is connected at one end to the upper end of the operating lever 15 and at its opposite end to an arm 20 projecting from a rock-shaft 21. A spring 22 has one end connected to the end of the strap 19 which is attached to the clutch-operating lever 15 and the opposite end of the spring is anchored to the casing 3, see Fig. 2, to cause it to rock the operating lever into engagement with the beveled flange 14 of the clutch 13 to release it from driving engagement with the helical gear 12.

A spindle-cup 25 is keyed to the end of the spindle 10 projecting outwardly from the casing 3. As illustrated in detail in Fig. 16, the spindle-cup is in the form of a sleeve slidably mounted on the spindle 10 and having a head at its outer end with a concavity or recess 26 for receiving the butt end of a bobbin b. Preferably, an annular resilient lining 27 having a conical face is provided in the recess 26 for yielding engagement with the bobbin b. A central guide-stem 28 having its flanged head secured fast in the bore of the spindle-cup 25 projects rearwardly axially thereof and is adapted for sliding movement in an axial bore 29 in the end of the spindle 10. A helical spring 30 mounted in the bore 29 of the spindle 10 normally acts against the

end of the stem 28 on the spindle-cup 25 to yieldingly propel the latter outwardly to engage the bobbin b. The spindle-cup 25 is thus retractable on the spindle 10 to release the butt end of the bobbin b to doff the latter. An annular flange 31 projects radially from the periphery of the spindle-cup 25 in spaced relation to its outer enlargement or head to provide a peripheral recess or groove 32 into which a roller 33 at the end of an operating arm 34 projects.

The outer end of the bobbin b is supported in the cupped end 38 of a stub-spindle 39, see Fig. 18, rotatably mounted in a bearing in axially spaced relation to the spindle-cup 25 on the spindle 10. The bearing 40 for the stub-spindle 39 is carried by a part of a frame 41 attached to a bracket 42 by means of screws 43, the bracket projecting forwardly from the front of the casing 3, see Figs. 1, 2, 4, 9 and 21. By means of this arrangement the bobbin b is adapted to be clamped between the spindle-cup 25 on the spindle 10 and the cup-shaped end 38 of the stub-spindle 39 to be rotated from the spindle-drive shaft 4 through the helical gears 11 and 12 and clutch 13.

Traversing mechanism and its operating means

The winding unit comprises means for traversing the yarn on the bobbin b and progressively advancing the range of traverse longitudinally of the bobbin during the winding operation to cause the yarn to be wound in overlapping layers to produce a shuttle cap with a filling wind. Referring to Figs. 1 and 2 of the drawings, the traversing means consists in a thread-guide 45, a two-part traverse rod 46, 64 on which the thread-guide is mounted and a cam 47 for longitudinally reciprocating the traverse rod. The cam 47 is pinned to a horizontal shaft 48 extending transversely of the traverse-drive shaft 5 and journaled in suitable bearings in the front and back walls of the casing 3. The shaft 48 is driven from the drive shaft 5 by intermeshing helical gears 49 and 50 and a clutch 51 having a beveled flange 52, these elements of the drive being similar to the gears 11 and 12 and clutch 13, previously described, for driving the spindle 10. The clutch 51 is splined to the hub of the cam 47 and adapted to be held in engagement with the gear 50, loose on the shaft 48, by yieldable means, not herein shown. An operating lever 53 is rockably mounted at its lower end on a bracket 54 for movement in a plane at right-angles to the axis of the shaft 48 to cause it to engage the flange 52 of the clutch 51 to disconnect the drive. A strap 57 has one end connected to the upper end of the operating lever 53 and its opposite end connected to an arm 58 on the rock-shaft 21. A spring 59 is also provided having one end connected to the end of the strap 57 attached to the operating lever 53 and its opposite end anchoring to the casing 3. The driving connection from the traverse-drive shaft 5 to the shaft 48 is thus identical in construction with the driving connection from the spindle-drive shaft 4 to the spindle 10 and the clutches 13 and 51 are adapted to be simultaneously operated to start the winding operation by rocking movement of the rock-shaft 21 to disengage the operating levers 15 and 53 from the flanges 14 and 52 on the clutches. 70 To arrest the winding operation the levers 15 and 53 are rocked by the springs 22 and 59 to engage the levers with the clutches to withdraw them from the gears.

The cam 47 is of usual construction having a helical groove 60 in its periphery. An oscillatable

lever 61, see Figs. 1 and 2, pivotally mounted on an axis below the shaft 48 has a pin 62 at its upper end carrying a roller 62^a projecting rearwardly into the groove 60 of the cam. The upper end of the lever 61 is U-shaped with a flange 63 connected to the rearward end of a link 56 which, in turn, is connected to the end of the traverse rod section 46. As illustrated in Fig. 1, the flange 63 has a series of holes therein for connecting it to the end of the link 56 whereby to adjust the length of the stroke of the traverse rod. It will be observed from the above description that the rotation of the drive shaft 5 transmitted through the helical gears 49 and 50, clutch 51, shaft 48 and cam 47 is translated into reciprocation of the 15 traverse rod by the oscillating lever 61.

As before indicated, the traverse rod has two sections comprising the portion connected to the link 56 which will hereinafter be referred to by the reference character 46, and a relatively rotatable threaded section 64. The traverse rod section 46 is slidably mounted in a guideway 65 formed in a bearing member 66 extending parallel to the spindle 10 and supported in part on the spindle 10 and in part by the front wall of the casing 3, see Fig. 2. Referring now to Figs. 4 and 5, the rearward end of the threaded outboard section 64 of the traverse rod is connected to the forward end of the main section 46 by a coupling 67 which permits articulation between the two sections. The forward end of the section 64 is mounted for rotation and reciprocation in a bearing 68 supported by an outboard bracket 76 fastened to the frame 41, previously described. The bearing 68 is pivotally mounted in an opening in the bracket 76 by means of a pin 69 at the top of the bracket, see Fig. 4, to permit the rod section 64 to swivel as it is swung toward or away from the winding spindle.

Referring to the enlarged view, Fig. 5, the 40 coupling 67 comprises a member 70 having a tapered bore 71 into which the tapered end of the traverse rod section 46 is driven with a force fit to connect the two parts. The member 70 is of bifurcated construction, see Fig. 8, to provide a horizontal slot 72 in which a cooperating member 73 of the coupling is adapted to slide. A stud 74 projecting through the member 70 and a vertical slot 75 in the member 73 limits the sliding movement of the latter in a path toward and away 45 from the winding spindle 10 as indicated by dash-lines in Fig. 5. The member 73 is provided with a laterally-projecting threaded stud 78 and the rearward end of the threaded traverse rod section 64 is connected thereto by a thimble 79 which forms a bearing for the traverse rod section and has internal threads to adapt it to be screwed onto the threaded stud. The stud 78 is formed with an axially-projecting stem 81 received in a bore in the end of the traverse rod section 64 to maintain the parts in alignment. Preferably, the threaded traverse rod section 64 has an annular shouldered projection 80 adapted to rotate in a bore 81 at the end of the thimble 79, a collar 82 being secured fast on the end of the rod section between the projection and the end of the stud 78. Forwardly of the annular bearing shoulder 80 the traverse rod section 64 has a plain portion 86 without threads and of the same diameter as the root diameter of its threaded portion.

The inner end of the threaded traverse rod section 64 is connected to the coupling member 73 by screwing the thimble-like bearing 79 onto the threaded stud 78 until the collar 82 abuts the end 75 of the stud with its opposite end engaging the end

wall of the thimble; this construction providing for free rotation of the threaded traverse rod section relatively of the rod section 46. The thimble 79 is clamped in adjusted position on the stud 78 by means of a strap 83 which embraces the periphery of the thimble. The thimble 79 is formed with a series of longitudinal slots 84 to adapt the sections between the slots to flex into binding engagement with the stud 78, see Fig. 7. A screw 85 extends through a hole in one end of the strap 83 and is threaded into a hole in the opposite end thereof to bind the strap around the thimble 79. The traverse rod section 64 is thus connected to the main section 46 for rotatory movement relative thereto and to adapt it to swing inwardly toward the winding spindle from the position shown in full lines to that indicated by dash lines in Fig. 5.

A former-bar 88 is mounted on the upper face 20 of the coupling member 70 by means of screws 89 which extend through slots 90 in the former-bar to adapt it for angular adjustment on the coupling member. Attached to the under side of the coupling member 70 by means of screws 92 is a depending guiding keel 93 which projects through a slot 94 in a bracket 77 projecting outwardly from the casing 3, see Fig. 8, to restrain the coupling 67 from rotation. The coupling member 73 and the inner end of the traverse rod section 64 are normally urged outwardly to the position illustrated in full lines in Fig. 5 by means of a spring 95 anchored at one end to a lug on the clamping strap 83 and connected at its other end to a lug on the guide member 93, the outward movement of the coupling member 73 and the inner end of the traverse rod section 64 being limited by the engagement of the end of the slot 15 with the stud 74.

The thread-guide 45 is mounted on the threaded traverse rod section 64 and comprises a plate-like arm 99 extending laterally to overlie the bobbin b with a thread-eye 100 of vitreous material carried at its end, see Fig. 5. The thread-guide 45 is of bifurcated form with depending flanges 97 and 98 having bearing apertures therein in which a rotatable nut 101 is journaled, see Fig. 6. The nut 101 has a smooth bore throughout the greater portion of its length closely fitting the periphery of the threads of the traverse rod section 64 and a shorter interiorly-threaded portion 102 at its left-hand end as viewed in Figs. 5 and 6 in engagement with the threads on the traverse rod section. The length of the threaded portion 102 of the bore in the nut 101 is slightly less than the length of the plain portion 86 at the rearward end of the traverse rod section 64 whereby to permit disengagement of the nut from the threads of the traverse rod when the thread-guide 45 is moved to its rearmost position thereon. The nut 101 has a hub 103 adjacent the side of the thread-guide 45 on which a contact-wheel 104 is fixedly mounted. Rotation of the nut on the threaded traverse rod section 64 by the engagement of the contact wheel with the periphery of the bobbin, or rotation of the traverse rod section with respect to the nut will effect longitudinal movement of the thread-guide along the traverse rod in one direction or the other. A friction element 105 in the form of a helical spring is mounted on the thread-guide arm 99 with one end bearing against the contact wheel 104. As illustrated in Fig. 6, the friction element 105 is coiled about a screw 106 with one end anchored to a knurled washer 107 on the screw and its opposite end projecting lat-

erally into engagement with the side of the contact wheel, see Fig. 5. Projecting laterally from the depending flange 97 of the thread-guide 45 is a finger 108 adapted to ride along the inclined edge of the former-bar 88 to force the inner end of the traverse rod section 64 toward the winding spindle 10 when the thread-guide is returned to position to start the winding of a bobbin. A leaf-spring 109 is mounted on the side of the finger 108 to adapt it to engage with the end of the thimble 79 as illustrated in dash-lines in Fig. 5 to re-engage the threaded portion 102 of the thread-guide nut 101 with the threads of the traverse rod section 64 after it has been carried back onto the plain portion of the rod section. Depending from the flange 98 of the thread-guide 45 is a tail-piece 110, see Fig. 4, which projects through the slot 94 in the bracket 77 to restrain the thread-guide from turning on the traverse rod.

The yarn may be supplied to the bobbin being wound from a source of supply 113, see Fig. 1, with the strand *y* leading upwardly therefrom through a tension-device 114, thence through a resiliently suspended guide 115, and then downwardly through the eye of a drop wire 116 and the eye 100 of the thread-guide 45. The tension-device 114 as herein illustrated is generally similar to that shown and described in detail in the United States Letters Patent of Ernest R. Swanson, No. 2,236,459, dated March 25, 1941. This type of tension-device comprises opposed tension-members normally pressed into engagement with the yarn strand and adapted to be actuated by an electromagnet 117 to open the tension-members when energized under certain conditions as more fully explained hereinafter.

The traversing mechanism of the machine operates in the usual manner to reciprocate the threaded-guide 45 with a limited stroke to cause the yarn *y* to be wound in crossing coils on the bobbin *b*. At the beginning of the winding operation the finger 108 on the thread-guide 45 bears on the inclined edge of the former-bar 88 to maintain the inner end of the traverse rod section 64 in the position indicated in dash-lines in Fig. 5 against the action of the spring 95. The contact wheel 104 is rotated by its engagement with the periphery of the bobbin *b* to turn the nut 101 to advance the thread-guide 45 longitudinally of the threaded traverse rod section 64. As the thread-guide 45 advances along the threaded traverse rod section 64 the rearward end of the bobbin *b* is built up with a taper corresponding to the incline of the edge of the former-bar 88 until the inner end of the traverse rod section 64 has been moved outwardly by the spring 95 to the position illustrated by full lines in Fig. 5, as effected by the sliding advance of the finger 108 along the edge of the former-bar. The winding operation continues in the usual manner to deposit the yarn in advancing layers as the thread-guide 45 is fed progressively along the threaded traverse rod section 64 to complete the bobbin *b*.

Thread-guide return means

After a fully wound bobbin *b* has been doffed the thread-guide 45 is automatically returned to initial winding position by rotating the threaded traverse rod section 64 by motion derived from the controller drive shaft 6. Referring to Figs. 1, 4 and 15 of the drawings, a sprocket 120 is splined to the outer end of the traverse rod section 64. As illustrated in Fig. 4 the sprocket 120

is held against reciprocatory movement with the rod section 64 by the engagement of the end of its hub with a plate 121 attached to the bracket 76 and at its opposite end by its engagement with the end of the bearing 68. A set-screw 122 in the sprocket 120 extends into a longitudinal spline or slot 123 in the traverse rod section 64 whereby the latter may reciprocate with respect to the sprocket but is connected rotatively therewith. The sprocket 120 is driven from a sprocket 124 at the end of a horizontal shaft 125 by means of a chain 126. The shaft 125 extends rearwardly in parallel relation to the traverse rod section 64 and is journaled in suitable spaced bearings 127 and 128 carried by the bracket 42. A bevel gear 129 at the rearward end of the shaft 125 meshes with a bevel gear 130, see Figs. 4 and 9, at the end of a horizontal shaft 131 extending longitudinally of the machine at the front of the casing 3. The shaft 131 is journaled in suitable bearings in brackets 132 and 133 projecting from the front of the casing 3. At the opposite end of the shaft 131 from the end carrying the gear 130 is a bevel gear 134, see Fig. 9, which meshes with a bevel gear 135 on a horizontal shaft 136 extending transversely through the casing 3, see Fig. 39. The opposite ends of the shaft 136 are journaled in antifriction bearings 137 and 138 in the casing 3 and the shaft is enclosed in a tubular housing 139 extending across the casing. Mounted on the rearwardly projecting end of the shaft 136 at the rear of the casing 3 is a helical gear 144 which meshes with a helical gear 145 rotatable on the controller drive shaft 6, see Fig. 39.

Referring to Figs. 34 and 35, the controller drive shaft 6 is journaled in bearings 146 projecting from the brackets 9 bolted to the rearward wall of the casing 3. The helical gear 145 is rotatably mounted on a sleeve 149 journaled in a bearing 147 supported by a bracket 148 bolted to the casing 3. The gear 145 abuts the end of the bearing 147 and has laterally projecting pins 150 at its opposite side which project into slots 151 formed in the face of a male clutch element 152. The clutch element 152 is journaled on the sleeve 149 to adapt it to be slid longitudinally of the shaft 6 to engage it with or disengage it from a female clutch element 153 rotatably connected to the shaft by means of a set-screw 154. The male clutch element 152 has an annular groove 155 in which a roller 156 on a shifting lever 157 engages. The shifting lever 157 is pivoted on a stud 158 projecting rearwardly from the bracket 148 above the controller drive shaft 6. The male clutch element 152 is normally held disengaged from the female clutch element 153 by means of a spring 159 connected at one end to the lower end of the shifting lever 157 and anchored at its opposite end to a lug 160 on the bracket 148. The male clutch element 152 is shifted into operative engagement with the female clutch element 153 by means of an electromagnet or solenoid 161 having a plunger 162 connected to the shifting lever 157 by means of a spring 163.

The spring 163 is considerably stronger than the spring 159 so that when the solenoid 161 is energized the shifting lever 157 is moved against the tension of the spring 159 to clutch the gear 145 to the controller drive shaft 6. The shaft 6 operates through the gearing previously described to rotate the traverse rod section 64 to return the thread-guide to initial winding position. Due to the engagement of the friction element 105 on the thread-guide 45 with the side of the contact

wheel 104 the nut 101 is restrained from turning on the rod section 64 as the latter is rotated and therefore the thread-guide will be fed rearwardly therealong.

When the thread-guide 45 has been returned to initial winding position the threaded portion 102 of the nut 101 will be carried onto the unthreaded portion 86 of the traverse rod section 64 to prevent further rearward movement of the guide, the leaf-spring 109 being flexed at this juncture as it engages with the end of the thimble 79. The spring 109 will thus act to yieldingly urge the thread-guide nut 101 into meshing engagement with the threads on the traverse rod section 64 at the beginning of another winding operation. Upon deenergization of the solenoid 161 the spring 109 acting through the shifting lever 157 disengages the male clutch element 152 from the female clutch element 153 to arrest rotation of the gear 145. The energization and deenergization of the solenoid 161 effects the return of the thread-guide to initial winding position and is controlled in a manner to be explained hereinafter.

Yarn-retriever

After a bobbin B has been completed and before rotation of the spindle 10 is arrested a yarn-retriever 170 operates to perform the several functions of traversing the yarn strand y rearwardly on the bobbin to form a back wind W, position the strand to adapt it to be attached to an empty bobbin b being donned and restrict the traverse of the yarn at the beginning of a new winding operation to form a bunch at the rearward end of the bobbin b. Referring to Figs. 1, 2, 4 and 20, the yarn-retriever 170 is illustrated as in the form of a horizontal blade having a finger 171 projecting parallel to the axis of the winding spindle 10, an inclined edge 172 extending forwardly from the finger and a flange 173 folded upwardly from the side of the blade to provide a crotch 174. The upwardly folded flange 173 extends to the left from the crotch 174 to a position adjacent the end of the finger 171 and at its opposite end is bent rearwardly in an arc. By this form of construction the finger, flange and inclined edge 172 serve as a means to direct the yarn strand y leading from the thread-guide 45 into the crotch 174.

A flange 175, see Figs. 4 and 20, extends upwardly from the edge of the yarn-retriever blade opposite the flange 173 with its lateral portions folded around to engage across the edge of a flange 176 depending from a supporting slide 177. The flange 175 is attached to the flange 176 by means of a screw 178 to thereby support the yarn-retriever 170 from the slide 177. The screw 178 extends through a slot 179 in the yarn-retriever flange 175 to permit vertical adjustment of the yarn-retriever with respect to the slide, see Fig. 15.

The slide 177 extends rearwardly from the depending flange 176, as viewed in Fig. 4, and has a bifurcated bracket 180 welded or otherwise attached to its under side. Laterally spaced ears 181 and 182 project upwardly from the bracket 180 and are formed with apertures for receiving a stationary rod 183 to slidably support the slide thereon. The supporting rod 183 is mounted above the spindle 10 in parallel relation to its axis, being held at its opposite ends in suitable bearings 184 and 185 in the framework of the machine. The slide 177 is thus mounted for sliding movement longitudinally of the bobbin B and

the yarn-retriever 170 is so positioned vertically as to adapt it to travel between the bobbin and the thread-guide 45 to form a loop or bight in the yarn strand y.

The slide 177 has angularly related arms 190 and 191 which project upwardly at the rear of the supporting rod 183 with a plate portion 192 at their upper ends folded rearwardly with respect thereto, see Figs. 2 and 4. The rearwardly folded portion of the plate 192 is formed with a slot 193 through which the end of an operating lever 194 extends. The lower end of the operating lever 194 has a longitudinally extending slot 195 which embraces a stud 196 projecting rearwardly from the slide 177. The upper end of the lever 194 is pivotally mounted on a stud 197 carried at the outer end of a bracket 198 projecting outwardly from a stanchion 199 attached to the machine casing 3 by bolts 200. The lever 194 is thus adapted to be rocked on its pivot to cause the slide 177 to be moved from the position illustrated in Fig. 4 to that illustrated in Fig. 15, the engagement of the lever through the slot 193 in the slide acting to restrain the latter against rocking movement on the supporting rod 183.

The lever 194 is adapted to be actuated by a link 204 pivotally connected thereto by means of a stud 205 with the opposite end of the link connected to one arm 206 of a bell-crank lever 207 by a pivot-stud 208, see Fig. 4. The bell-crank lever 207 is pivotally mounted on a stud 209 projecting from a boss 210 on the frame stanchion 199. The opposite laterally offset arm 211 of the bell-crank lever 207 is connected to a link 212 by a pivot-stud 213 which is adjustable in a slot 214 in the arm to vary the effective length thereof. The lower end of the link 212 is connected to the arm 215 of a bell-crank lever pivotally mounted on a stud 216 and the opposite arm 217 of this lever is connected to the plunger 218 of a solenoid 219 by a link 220, see Figs. 4 and 15. The solenoid 219 is suitably mounted on the bracket 42, previously described, and when energized the movement of the plunger 218 is transmitted through the various linkages and bell-crank levers described above to rock the lever 194 and thereby move the slide 177 and yarn-retriever 170 from the position illustrated in Fig. 4 to that illustrated in Fig. 18. The link 220 is adjustable relatively to the solenoid plunger 218 by means of an eye-bolt 221 and lock-nut 222, see Fig. 15 which, together with the adjustable pivot-stud 213 for connecting the link 212 and arm 211 of the bell-crank lever 207, provide for adjusting the initial position of the slide 177 and regulating the extent of its rearward movement along the supporting rod 183.

As the yarn-retriever 170 moves rearwardly with the slide 177 from the position illustrated in Fig. 4 to that illustrated in Fig. 15 the yarn strand y is first engaged between the thread-guide 45 and the wound bobbin B and is guided by the finger 171 and flange 173 into the crotch 174 to be thereafter traversed rearwardly on the bobbin as the latter continues to rotate, whereby to form the back wind W indicated in Fig. 15.

The rearward movement of the yarn-retriever 170, is interrupted, however, by the interlocking engagement of an electromagnetically operated detent 226, see Figs. 15 and 17, with the plunger 218 of the solenoid 219, whereby the halting of the retriever will cause several extra coils to be wound on the base end of the bobbin B. The detent 226 is constituted by two laterally spaced

fingers 227 on a plunger 228 of a solenoid 229 arranged at right-angles to the solenoid 219 and attached to the side of the frame thereof. The detent-plunger 228 of the solenoid 229 has a stem 230 which projects rearwardly through the solenoid frame and a spring 231 coiled on the stem acts between the frame and the plunger to normally project the detent fingers 227 into position to be engaged by the laterally extending arms of the T-shaped plunger 218 of the solenoid 219, see Figs. 15 and 17.

After the wound bobbin B has been doffed in the manner as explained hereinafter, the yarn-retriever 170 moves rearwardly to a further extent to position the yarn strand y across the end of the spindle-cup 25 to adapt it to be clamped to the butt end of the empty bobbin b as the latter is gripped in the cup. This rearward movement of the yarn-retriever 170 is accomplished by energizing the detent-solenoid 229 to cause it to retract the plunger 228 against the action of the spring 231 to thereby release the armature 218 of the solenoid 219, see Figs. 17 and 18. Upon retraction of the detent-fingers 227 the plunger 218 of the solenoid 219 is further retracted from the position illustrated in Fig. 15 to that illustrated in Fig. 18 to cause it to act to move the slide 177 and yarn-retriever 170 rearwardly to a further extent along the rod 183. This latter rearward movement of the yarn-retriever 170 is limited in extent by an adjustable abutment in the form of a set-screw 232 on the bracket 198, see Figs. 4 and 18.

After an empty bobbin b has been donned the yarn-retriever 170 is moved forwardly from the position illustrated in Fig. 18 to that illustrated in Fig. 19 where it controls the yarn strand y to effect the winding of a bunch X at the base of the bobbin b. Upon deenergization of the solenoid 219 a spring 235 attached at one end to the bell-crank lever-arm 217 with its opposite end anchored to the bracket 42 acts to rock the bell-crank arm 215 to actuate the link 212, bell-crank lever 207, link 204 and lever 194 to carry the slide 177 forwardly on the rod 183 toward its inoperative position. During this forward movement of the slide 177 it is adapted to engage a detent 236 on a bobbin-releasing gate 392, described in detail hereinafter, to retain the yarn-retriever 170 in the position illustrated in Fig. 19. The reciprocating thread-guide 45 will then traverse the yarn strand y in the usual manner but due to the engagement of the strand by the inclined edge 172 and crotch 174 of the yarn-retriever 170 the length of traverse is restricted in the manner illustrated in Fig. 20 to cause a preliminary winding or bunch X to be formed. After the bunch winding has been completed the bobbin-releasing gate 392 is retracted in the manner explained hereinafter so as to withdraw the detent 236 from the slide 177. The yarn-retriever 170 will thus be released to return to its inoperative position at the forward or tip end of the bobbin b as illustrated in Fig. 4 by the action of the spring 235.

Starting and stopping means

After a bobbin B has been wound and the yarn-retriever 170 actuated to traverse the yarn rearwardly to form the back wind W the rotation of the spindle 10 and reciprocation of the thread-guide 45 are arrested. As previously explained, the rotation of the spindle 10 and reciprocation of the thread-guide 45 are initiated by rocking the rock-shaft 21, illustrated in Fig. 2, to disengage the operating levers 15 and 53 from the flanges 14 and 52 of the clutch elements 13 and 51; and

the operation of the winding elements is arrested by the engagement of the operating levers with the clutch-flanges under the action of the springs 22 and 59 to withdraw the clutch-elements from the helical gears 12 and 50.

The forward end of the rock-shaft 21 projects through the front wall of the casing 3 and has an operating handle 240 fastened thereto, see Figs. 9 and 10. The winding operation may be started by rocking the handle 240 in a counterclockwise direction as viewed in Fig. 9 to rock the rock-shaft 21 and the arms 20 and 58 to withdraw the clutch-operating levers 15 and 53 from engagement with the beveled flanges 14 and 52 of the clutch elements 13 and 51. When thus released the clutch elements 13 and 51 will be slid into driving engagement with the helical gears 12 and 50 by means of their springs, previously referred to but not herein shown, to connect the spindle 10 and traversing cam 47 to their respective drive shafts 4 and 5.

The starting handle 240 is in the form of a bell-crank lever having a laterally projecting arm 241 with a rearwardly projecting latching shoulder 242, see Figs. 9 and 10, adapted to be engaged by a detent-latch 243. The detent-latch 243 is in the form a bell-crank lever pinned to a rock-shaft 244 extending at right-angles to the rock-shaft 21 and journaled in suitable bearings on a bracket 252 fastened to the casing 3 of the machine. The detent-latch 243 has a latching shoulder 245 on its arm 246 engageable with the latching shoulder 242 on the starting handle 240 in the manner illustrated in Fig. 10. The latch 243 is normally urged into engagement with the latching shoulder 242 on the starting handle 240 by means of a spring 247 coiled around the rock-shaft 244 with one end bearing against the arm 246 and its opposite end held against an abutment on the casing 3, see Fig. 10. After the starting handle 240 has been rocked to starting position it is held by the latch 243 to maintain the clutch elements 13 and 51 in driving engagement with the gears 12 and 50.

The rotation of the spindle 10 and reciprocation of the thread-guide 45 are arrested automatically by means of a latch-trip mechanism comprising a solenoid 249 mounted on the bracket 252 at the front of the casing 3 and positioned directly below the end of the arm 248 of the latch 243. The solenoid 249 has a plunger 250 with a contact rod 251 extending therefrom through the supporting frame to adapt it to engage the outer end of the arm 248 of the latch 243. Upon energization of the solenoid 249 the contact rod 251 will be moved with the plunger 250 to engage the end of the arm 248 to rock the latch 243 against the tension of the spring 247, whereby to release the starting handle 240. Upon release of the starting handle 240 the clutch operating levers 15 and 53, see Figs. 2 and 3, connected to the arms 20 and 58 on the rock-shaft 21 are actuated by the springs 22 and 59 to simultaneously engage the flanges 14 and 52 of the clutch elements 13 and 51 to disconnect the drive from the spindle 10 and traverse cam 47. A spring 253 connected to the plunger 250 and anchored to the casing 3 at 254 is adapted to withdraw the plunger into its inoperative position shown in Fig. 9.

After the wound bobbin B has been doffed and an empty bobbin b donned in its place the rotation of the spindle 10 and reciprocation of the thread-guide 45 are started again. The starting means comprise a bell-crank lever 256 which is rockably mounted on a laterally projecting hub

257 of the starting handle 240, see Fig. 10. One arm 258 of the lever 256 has a rearwardly projecting abutment 259 intermediate its ends which overlies the laterally extending arm 241 of the starting handle 240. The outer end of the arm 258 is connected to one end of a link 260, the opposite end of which is adjustably connected to the plunger 261 of a solenoid 262. Upon energization of the solenoid 262 the lever 256 is rocked in a counterclockwise direction as viewed in Fig. 9 so that the rearwardly projecting abutment 259 on the arm 258 will engage the laterally projecting arm 241 of the starting handle 240 to rock the latter into starting position. Upon this rocking movement of the handle 240 its arm 241 will be latched automatically to the latch 243 in the manner explained previously. It will be observed from the foregoing description that the rotation of the spindle 15 and reciprocation of the thread-guide 45 may be arrested automatically by energization of the latch-trip solenoid 248 and started automatically by energization of the solenoid 262. Upon deenergization of the solenoid 262 the bell-crank lever 256 is rocked to its initial position, illustrated in Fig. 9, by a spring 263 having one end connected to the solenoid plunger 261 and its opposite end anchored to the machine casing at 264.

A mechanical latch-trip is also provided for releasing the starting handle 240 in case the solenoid 249 should fail to operate the latch 243. As illustrated most clearly in Fig. 11, a collar 265 is rigidly attached to the projecting end of the rock-shaft 244 by means of a set-screw 266. Mounted on the collar 265 is an upwardly extending arm 267 adapted for rocking the shaft 244 on its axis independently of the latch-trip solenoid 249. The arm 267 is pivotally mounted on a stud 268 carried by the collar 265 to adapt it for rocking movement in a plane at right-angles to its plane of movement for actuating the rock-shaft 244 as indicated by dash-lines in Fig. 11. Projecting laterally from the lower end of the upright arm 267 is an arm 269 having a depending foot 270, see Figs. 11 and 12, with an inclined cam-surface 271 on one edge, see Fig. 13. The arm 267 is normally held in its upright position illustrated by full lines in Fig. 11 by the engagement of the side of the depending foot 270 on its arm 269 with a ledge 272 on a control member 272, see Figs. 12 and 16. Upon movement of the control member 272 to withdraw the ledge 272 from engagement with the depending foot 270, a spring 273 connected to the foot at one side of the axis of the pivot-stud 268 is adapted to rock the arm 267 to the position indicated by dash-lines in Fig. 11. As shown in Fig. 15, the control member 272 is carried by a sizing rod 274 slidably mounted in suitable bearings in the bracket 11 and having a collar 275 adjustable longitudinally thereof. The collar 275 is adapted to be engaged by the tail-piece 110 on the thread-guide 45 to slide the rod 274 whereby to initiate the functioning of the doffing and denning mechanism of the machine.

The normal sliding motion of the sizing rod 274 under the action of the thread-guide 45 is not sufficient to release the arm 267, but excessive movement thereof will withdraw the ledge 272 on the control member 272 away from the depending foot 270 and permit the latter to ride down the incline 278 on the control member adjacent the ledge, see Fig. 16, whereby the spring 273 will rock the arm 267 to the position indicated by dash-lines in Fig. 11. A bunter 276 on

the reciprocating traverse rod section 46, see Figs. 4, 5 and 11, is provided for engagement with the inclined arm 267 to rock the shaft 244 and thereby the latch-member 243 mounted thereon, which action will release the starting handle 240 and rock-shaft 21 to arrest rotation of the spindle 10 and reciprocation of the thread-guide 45. The cam surface 271 at the edge of the depending foot 270 on the arm 269 is adapted to cooperate with the inclined edge 278 adjacent the ledge 279 on the control member 272 whereby rearward movement of the control member will rock the depending foot into engagement with the ledge and move the arm 267 into upright position.

The latch-trip mechanism is also operative to rock the rock-shaft 244 to release the starting handle 240 upon breakage or exhaustion of the yarn supply. For this purpose the yarn strand extends through the drop-wire 116, previously mentioned, which is formed with a coiled portion providing a hub 283 for rockably mounting it on a pivot-stud 284 held in a bracket 281, see Figs. 4 and 11, an eye-supporting loop 285 and a curved tail-portion 286. The eye-supporting loop 285 is laterally offset at its upper end to adapt it to mount a circular eye 287 in position for the strand y to feed downwardly therethrough. The tail-portion 286 is so arranged as to overbalance the drop-wire 116 to cause it to pivot in a counterclockwise direction from the position illustrated in Fig. 11 to that illustrated in Fig. 12, the end of the tail-portion 286 being formed into a loop 288 adapted to intervene between the bunter 276 and the upright arm 267 on the rock-shaft 244.

The drop-wire 116 is normally held in its upright position illustrated in Fig. 11 by the yarn strand y feeding to the thread-guide 45, but upon breakage of the strand or exhaustion of the supply the bail is adapted to rock into the position illustrated in Fig. 12. Upon the next rearward movement of the traverse rod 46 the bunter 276 fast thereon will engage the loop 288 of the drop-wire 116 so that its tail-portion 286 will rock the upright arm 267 on the rock-shaft 244. It will be understood that the movement of the upright arm 267 is very slight and the tail-portion 286 of the drop-wire 116 will flex slightly during its movement by the bunter 276. Rocking movement of the rock-shaft 244 acts to rock the latch-arm 246 to disengage it from the latching shoulder on the starting handle 240 whereby to release the latter to cause the arrest of rotation of the spindle and reciprocation of the thread-guide 45 in the manner explained previously.

To return the drop-wire 116 to its upright position, illustrated in Fig. 11, at the beginning of a new winding operation an actuating rod 289, see Figs. 9 and 14, is provided having an offset shouldered portion 290 engageable with the tail portion 286 of the drop-wire. The actuating rod 289 has one end slidably mounted in a bearing 291 beneath the pivotal mounting for the drop-wire 116 while its opposite end is connected to the arm 292 of the bell-crank lever 256. Consequently, the rocking movement of the bell-crank lever 256 by the solenoid 262 will slide the rod 289 from the position illustrated in full lines in Fig. 14 to that indicated by dash-lines to engage the tail-portion 286 of the drop-wire 116 and move the latter to raise its tail-portion above the range of the bunter 276. The drop-wire 116 will thus be returned to upright position where it is held by the tension of the yarn strand as shown in Fig. 11. A lug 280 on the bracket 281 limits the return movement of the drop-wire 116 as shown

in Fig. 9. Upon deenergization of the solenoid 262 the spring 263 will act to rock the bell-crank lever 256 to the position illustrated in Fig. 9 whereby to return the actuating rod 289 to the position illustrated in Figs. 9 and 14. The drop-wire 116 is then free to rock upon breakage or failure of the yarn strand to initiate the operation of the stopping mechanism.

Doffing mechanism

After the back wind W has been completed on the bobbin B by the rearward movement of the yarn-retriever 170 and the rotation of the spindle 10 and reciprocation of the thread-guide 45 have been arrested the wound bobbin is doffed by retracting the spindle-cup 25. The operating arm 34 carrying the roller 33 which engages the flange 31 of the spindle-cup 25, see Fig. 16, constitutes one arm of a bell-crank lever 300, shown in Figs. 4, 9 and 18, pivotally mounted on a stud 301 projecting from the bracket 42.

As illustrated most clearly in Fig. 9 the bell-crank lever 300 is provided with a lateral extension or bar 302 disposed in parallel relation to the front of the casing 3 with a hub 303 at its opposite end and pivoted on a stud 304 held in a bracket 305 bolted to the casing. Projecting laterally from the bar 302 intermediate its ends is an actuating arm 306, see Figs. 9 and 18. The end of the arm 306 is connected by a link 309 to the plunger 307 of a solenoid 308 supported from the bracket 252. Upon energization of the solenoid 308 the plunger 307 is drawn downwardly and, acting through the link 309 and arm 306, it will rock the bell-crank lever 300 to cause the operating arm 34 to bear against the flange 31 of the spindle-cup 25 to retract the latter to the position illustrated in Fig. 18. Upon retraction of the spindle-cup 25 the wound bobbin B will fall by gravity to doff it from winding position. The energization of the solenoid 308 is maintained for a time interval to permit an empty bobbin b to be donned, and upon deenergization of the solenoid the spindle-cup 25 is propelled forwardly under the action of its spring 30, see Fig. 16. A spring 310, see Fig. 19, having one end connected to a depending arm 311 of the bell-crank lever 300 and its opposite arm anchored to the bracket 252 acts to return the bell-crank lever 300 and solenoid plunger 307 to their initial positions. A set-screw 312, see Figs. 18 and 19, carried by the bracket 252 serves as an adjustable stop to regulate the inoperative position of the bell-crank lever 300.

When the spindle-cup 25 is retracted to release the wound bobbin B the latter falls by gravity into a chute 315 positioned directly therebeneath and closely adjacent thereto, see Figs. 29 to 32. The chute 315 is of rectangular form in plan view, see Fig. 30, with a narrow ledge 316 projecting inwardly from one side at the top thereof. A pivoted gate 317 within the chute 315 is adapted to temporarily detain the wound bobbin B prior to the attachment of its trailing yarn strand to the fresh bobbin b. The gate 317 extends throughout the length of the chute 315 in inclined relation to both the vertical and horizontal, see Figs. 29, 30 and 31, being pivotally mounted at one side on a rod 318. The gate 317 is normally maintained in the position illustrated in Fig. 31 by an operating rod 319 mounted to slide in bearings at one end of the chute. The end of the rod 319 engaging the gate 317 is of U-shape with its parallel legs projecting through spaced apertures in one side of the chute 315 to

restrain the rod from turning. A collar 320 fast on the rod 319 provides an abutment for one end of a spring 321 which acts between the collar and side of the chute to yieldingly hold the rod in the position illustrated by full lines in Fig. 31. The longer leg 322 of the rod 319 projects through a bearing 323 in the wall of the chute. It will be observed by reference to Fig. 29 that when the doffed bobbin B enters the chute 315 it will be guided against one of the side walls by the lateral inclination of the gate 317, see Fig. 31, and is slanted downwardly, see Fig. 29, due to the longitudinal inclination of the gate.

A yarn-trap 328 is provided at the top of the chute 315 for engaging the yarn strand y trailing from the doffed bobbin B and guiding it into position to be severed. The yarn-trap 328 comprises a plate 329 pivotally mounted on a rod 330 extending longitudinally of the top of the chute 315. The rod 330 is mounted in angular brackets 331 and 332 depending from the horizontal ledge 316 of the chute 315, see Figs. 29 and 30. The angular brackets 331 and 332 are fastened to the ledge 316 by screws 333 and 334 projecting through slots 335 and 336 therein, thus permitting adjustment of the brackets. The brackets 331 and 332 are apertured to receive the ends of the rod 330 which is held against longitudinal movement therein by collars 337. The rod 330 extends through apertures in the depending ears 339 and 340 on the plate 329 which is yieldingly held in its horizontal position overlying the top of the chute 315 by means of a helical spring 341 mounted on the rod with one end anchored to the ledge 316 and its other end underlying the plate. A set-screw 324, see Fig. 31, at the top of the chute 315 acts as a stop to limit the upward swinging movement of the plate 329. The tension of the spring 341 is comparatively light whereby the falling bobbin B is adapted to swing the plate 329 downwardly to permit the bobbin to pass thereby.

At the left-hand end of the plate 329, as viewed in Fig. 30, a portion 348 thereof is folded downwardly and inwardly, see Fig. 32, to provide a guiding shoulder 349 for the yarn strand y. A strand-engaging element 350 in the form of an angular plate has a horizontally extending portion 352 for cooperation with the shoulder 349 and a depending tail portion 351 which is so constructed and arranged as to normally rock the horizontal portion toward the shoulder 349. The angular plate 350 has a pivot pin 353 welded or soldered thereto with its projecting ends pivoted in the spaced ears of a bracket 355 attached to the under side of the plate 329 by means of screws 356, see Figs. 30 and 32. A knife 357 mounted on the top face of the plate 329 by means of one of the screws 356 extends laterally across and beyond the shoulder 349 of the plate, see Fig. 32.

As the doffed bobbin B drops into the chute 315 the plate 329 pivots on the rod 330 against the action of the spring 341 and the trailing yarn strand y engages the outer edge of the plate. As the bobbin B falls beyond the plate 329 and assumes the inclined position on the gate 317 illustrated in Fig. 29, the plate 329 swings back to the position illustrated in Fig. 31 and the strand y is carried against the edge of the plate 350. Due to the position of the yarn-retriever 170 and the doffed bobbin B in the chute 315 the strand y will be guided between the edge of the portion 352 of the plate 350 and the shoulder 349 of the plate 329 as illustrated in Fig. 32. The engagement of

the yarn strand *y* between the plate 350 and shoulder 349 of the plate 329 insures that the strand will be positioned across the end of the spindle-cup 25. Due to the draft on the trailing strand *y* as the spindle-cup 25 rotates in a clockwise direction as viewed in Fig. 33 to drive the donned bobbin *b* the strand is engaged with the edge of the knife 357 to cause it to be severed.

The rod 319 for holding the gate 317 in its normal position illustrated in Fig. 31 is slid 10 against the action of the spring 321 to release the gate by means of a solenoid 362. The solenoid 362 is mounted on a bracket 361 which, in turn, is supported on the bracket 42, see Figs. 30 and 31. The solenoid 362 has a plunger 363 with an extension 364 engageable with the end 322 of the rod 319. Upon energization of the solenoid 362 the gate 317 is released to adapt it to drop by gravity to the position indicated by dash-lines in Fig. 31 to thereby release the wound bobbin *B*. It will be understood that the energization of the solenoid 362 is subsequent to the return of the thread-guide 45 to initial position where it releases the loop or bight formed in the yarn strand by the initial operation of the yarn-retriever 170. This takes place prior to the donning of an empty bobbin *b* so that the falling bobbin will take the slack in the loop and draw the length of strand 20 between the yarn-retriever 170 and yarn-trap 328 taut across the end of the spindle-cup 25, see Fig. 33. Upon deenergization of the solenoid 362 the spring 321, acting between the side of the chute 315 and the collar 320, will move the rod 319 to the position illustrated by full lines in Fig. 31 to swing the gate 317 back to its normal position.

The sides of the chute 315 at the lower ends thereof are provided with laterally projecting flanges 367 and 368 for slidably mounting a box or container 369 having cooperating flanges 370 and 371, see Fig. 31. The container 369 is adapted to be slid into position manually to suspend it from the bottom of the chute 315, a handle 372, see Fig. 29, being provided for this purpose. It is to be noted that due to the inclination of the gate 317 the wound bobbins *B* drop through the chute 315 butt end first so that this end will strike the butt end of the other bobbins in the container 369 and thus prevent damage to the yarn wound thereon.

Donning mechanism

After the spindle-cup 25 is withdrawn to doff the wound bobbin *B* an empty bobbin *b* is positioned between the spindle-cup and the cupped end 38 of the stub-spindle 39 to adapt it to be donned. The donning mechanism comprises a magazine 375 for holding a supply of empty bobbins *b* and a bobbin-transferring cradle 376 for transferring the empty bobbins from the magazine into alignment with the spindle-cup 25 and stub-spindle 39. The magazine 375 comprises a pair of laterally spaced chutes 377 and 378 for receiving the ends of the bobbins *b*, see Fig. 21. The chute 377 is of U-shape, see Fig. 2, and dimensioned to adapt it to receive the head of the bobbins *b*, a plate 379 being attached to one wall thereof as by welding or brazing. The chute 377 is attached to the bracket 198 projecting from the stanchion 199, see Figs. 4 and 21, by means of screws 380 projecting through slots 381 in the bracket and screwed into the plate 379, the latter having a lip 382 overlying the top of the bracket to properly position the chute, see Figs. 21 and 26. The chute 377 may be adjusted laterally to a limited extent by releasing the screws 380 and sliding them in the slots 381. A laterally ex-

tending plate 386 is integrally attached at one end to the rearward side of the chute 377, see Figs. 2 and 4, and has relatively long spaced slots 387 adjacent its outer end.

The chute 378 is of U-shape similar to that of the chute 377 but of lesser width to adapt it to receive the smaller end of the bobbins *b*. The chute 378 is mounted on the outer end of the plate 386 by means of screws 388 passing through the slots 387 and screwed into a plate 389 on the rearward side of the chute. The plate 389 is similar to the plate 379, previously described, being welded or brazed to the chute 378 and having a lip 390, see Figs. 21 and 23, overlying the upper edge of the mounting plate 386 to properly locate the chute. The slots 387 in the plate 386 permit a considerable lateral adjustment of the chute 378 with respect to the chute 377 to adapt the magazine to accommodate bobbins *b* of different sizes. As will be noted by reference to Fig. 21 the lowermost bobbin *b* in the magazine is positioned horizontally but due to their enlarged heads the other bobbins assume an angular position as illustrated in Fig. 21 as they are stacked one over the other. A curved flange 391, shown in Figs. 21 and 24, depends from the lower end of the rearward wall of the chute 377 for guiding the empty bobbins *b* at a point adjacent their heads. As illustrated in Fig. 23, the lower end of the chute 378 is curved to a contour corresponding to the curvature of the guiding flange 391 on the chute 377, these curved portions being adapted to cooperate to direct the empty bobbins forwardly as they descend from the magazine by gravity.

A pair of retaining gates 392 and 393 are provided for progressively engaging the empty bobbins *b* to retain the supply in the magazine, see Figs. 21 and 24. The gate 392 is in the form of a U-shaped frame having a longitudinally extending front bar 394 and rearwardly projecting arms 395. The rearward ends of the arms 395 are pivotally mounted on studs 396 and 397 projecting inwardly from the outer bracket 41 and the stanchion 199 at the front of the casing 3. Thus the gate 392 is mounted for rocking movement on its pivots 396 and 397 to shift it from the position shown in Fig. 23 to that shown in Fig. 25. An angular finger 398 mounted on the front of the gate 392 projects downwardly and rearwardly to adapt it to engage the next to the lowermost bobbin *b* in the magazine at a point adjacent its head, see Figs. 23 and 24. As illustrated in Fig. 21 the angular finger 398 is mounted on the gate 392 by means of a screw 399 projecting through a longitudinally extending slot 400 in the front bar of the gate, the slot permitting longitudinal adjustment of the finger to a position where the latter will engage the empty bobbin substantially at its center of gravity. The left-hand arm 395 of the gate 392 has an angular slot 401 of the shape illustrated in Fig. 26.

The gate 393 is similar in form to the gate 392 having a front bar with a depending lip portion 403 and rearwardly projecting arms 407 at its ends. The front bar and arms 407 of the gate 393 are slightly longer than the front bar and arms 395 of the gate 392 whereby to adapt the gate 393 to straddle the gate 392 and swing on an arc of greater radius. The ends of the arms 407 of the gate 393 are pivoted on studs 396 and 397 closely adjacent the arms 395 of the gate 392. The depending lip 403 of the gate 393 is thus adapted to swing on an arc of greater

radius than that of the gate 392 to cause it to engage the lowermost bobbin to detain it in the magazine 375. The left-hand arm 407 of the gate 493 is provided with a curved slot 409 of the form illustrated in Fig. 26. The two gates 392 and 393 are adapted to be operated in alternate relationship, that is, when one of the gates is raised the other one is lowered, and vice versa, the gates being operated by a pin 432 projecting laterally from the cradle 376 and adapted to slide in the slots 401 and 409 as will be explained hereinafter.

The bobbin-transferring cradle 376, see Figs. 21 and 22, is also in the form of a U-shaped frame having a front bar 410 with right-angular arms 411 and 412 projecting rearwardly from its ends. The length of the bar 410 of the cradle is greater than that of the front bar of the gate 393 to adapt the arms 411 and 412 to straddle the arms 407 of the gate. The ends of the arms 411 and 412 of the cradle 376 are pivotally mounted on the rod 183 which mounts the slideable yarn-retriever 170, see Figs. 4, 21 and 22, to adapt the cradle to rock from the position illustrated in Fig. 23 to that illustrated in Fig. 25.

Mounted in spaced relationship on the bar 410 of the cradle 376 are bobbin-grippers 413 and 414, shown in Figs. 21 and 22. The bobbin-grippers 413 and 414 are of similar construction each having an angular plate 417 with one end adjustably mounted on the bar 410 of the cradle by means of bolts 418, see Figs. 21 to 24. The bolts 418 extend through spaced slots 419 and 420 in the angular portion of the plate 417 which overlies the bar 410 of the cradle, see Fig. 21, and through a longitudinally extending slot 421 in the bar. Thus the plates 417 are adjustable on the bar 410 toward and away from each other to adapt them to grip bobbins of different sizes and also adjustable laterally of the bar to adapt them to locate the empty bobbins *b* accurately between the spindle-cup 25 and stub-spindle 39. Each gripper 413 and 414 has spaced fingers 422 and 423 mounted thereon for gripping the bobbins therebetween. The finger 422 is in the form of an angular bracket mounted on the outer portion of the gripper-plate 417 by means of a screw 424 extending through a slot 425 in the plate to adapt the latter for adjustment toward and away from the finger 423. The gripper-finger 423 is in the form of a plate having ears 426 and 427 positioned between and closely adjacent to ears 428 and 429 folded downwardly from the sides of the plate 417, see Figs. 21 and 23. Each gripper-finger 423 is pivotally mounted on a pin 430 extending through aligned apertures in the ears 428, 429 and 426, 427 on the finger and plate. The gripper-fingers 423 are urged yieldingly toward the fingers 422 by means of helical springs 431 coiled around the pins 430 with one end bearing against the plates 417 and the opposite end bearing against the finger, see Figs. 21 and 26.

It will be observed that except for the difference in dimensions of the parts the two grippers 413 and 414 are of identical construction and in the retracted position of the cradle 376, illustrated in Figs. 23 and 24, the gripper fingers 422 and 423 are adapted to underlie the bottom of the magazine chutes 377 and 378. After an empty bobbin *b* has been delivered from the magazine 375 to the cradle 376 to be held in the grippers 413 and 414 the cradle is rocked to the position illustrated in Figs. 25 and 26 to align the bobbin with the spindle-cup 25 and 75

stub-spindle 39 in position to be donned; and upon retraction of the cradle to initial position the fingers 423 are adapted to rock on the pivot-pins 430 against the action of the springs 431 to release the bobbin after it is donned in the manner as illustrated in Fig. 27.

A pin 432 mounted on the side arm 411 of the cradle 376 projects laterally through the slots 401 and 409 in the left-hand arms 395 and 407 of the upper and lower gates 392 and 393, respectively, see Figs. 21 and 26. During the movement of the cradle 376 from the position illustrated in Fig. 24 to that illustrated in Fig. 26 the pin 432, acting in the slots 401 and 409 in the arms 395 and 407 of the gates 392 and 393 operates to simultaneously lower the lowermost gate 393 into bobbin engaging position and raise the upper gate 392 to release the bobbins in the magazine to permit them to descend into engagement with the lower gate. Upon return of the bobbin-transferring cradle 376 to the position illustrated in Fig. 24 the pin 432, again acting in the slots 401 and 409, operates to lower the upper gate 392 to engage its finger 398 with the next to the lowermost bobbin and raise the gate 393 to release the lowermost bobbin to permit it to descend into the cradle 376.

The bobbin-transferring cradle 376 is arranged to be actuated by a bell-crank lever rockably mounted on the rod 183 with its hub abutting a boss on the standard 199 and having one arm 435 adjustably connected to the arm 411 of the cradle by means of a bolt 436, see Figs. 21 and 22. The opposite arm 438 of the bell-crank lever is connected to an arm 439 of a second bell-crank lever by means of a link 440, the second bell-crank lever being pivotally mounted on the stud 396, previously described and shown in Fig. 21 as the pivot for the gates 392 and 393. The other arm 441 of the second bell-crank lever is pivotally connected to the upper end of a link 442, see Fig. 22, which is joined at its lower end to an eye-bolt 443 adjustably connected to the plunger 444 of a solenoid 445. A spring 446, see Fig. 21, has one end connected to the eye-bolt 443 and its opposite end suitably anchored to the machine casing at 456. The arrangement is such that the spring 446 normally tends to raise the link 442 which, acting through the two bell-crank levers last described and the connecting link 440, will rock the cradle 376 from the position illustrated in Fig. 23 to that illustrated in Fig. 25, see Figs. 21 and 22. Upon energization of the solenoid 445 the link 442 is lowered to retract the bobbin-transferring cradle 376 to the position illustrated in Fig. 23.

The bobbin-transferring cradle 376 is normally retained in its retracted position, illustrated in Fig. 23, by means of a detent 447 see Figs. 21 and 28. The detent 447 is in the form of a plunger slidably mounted in a suitable frame 448 attached to the bracket 42 by means of screws 449. The end of the detent-plunger 447 is adapted to engage the end of a latch 450 secured to the bar 410 of the bobbin-transferring cradle 376 and depending therefrom, see Fig. 28. The detent-plunger 447 is urged upwardly into engagement with the end of the latch 450 by means of a spring 451 tensioned between the frame 448 and a collar 452 on the plunger. The detent-plunger 447 is adapted to be withdrawn from engagement with the latch 450 on the bobbin-transferring cradle 376 against the action of the spring 451 by means of a solenoid 453 attached to the frame

448. Upon energization of the solenoid 453 the 5 detent-plunger 447 will be withdrawn against the action of its spring 451 to release the bobbin-transferring cradle 376 and under the action of the spring 446, shown in Fig. 21, the cradle will be rocked to donning position. After the empty bobbin b has been gripped between the spindle-cup 25 and stub-spindle 39 and a bunch X wound thereon the solenoid 445 is energized to rock the cradle 376 to its bobbin-receiving position illustrated in Fig. 23, at which time the latch 450 will be engaged by the detent-plunger 447. The upper end of the plunger 447 is beveled to adapt the latch 450 to pass thereacross and thereafter the spring 451 will slide the plunger 447 into engagement with the latch to retain the cradle 376 in bobbin-receiving position.

Electric circuits and controller therefor

In accordance with the present invention the 20 several electromagnet windings are connected in different branches, designated C to M, of an electric circuit, each provided with a separate control switch designated C-1 to M-1, see Figs. 40 and 41. The opening or closing of the series of switches C-1 to M-1 is governed by a central controller 459 having cams designated C-2 to 25 M-2 for the branch circuits. The branch circuits C to M are connected in parallel, a conductor 460 joined to one end of each branch circuit being connected with a conductor 461 on one side of the power line; while a conductor 462 connects the opposite end of each branch circuit to the conductor 463 at the other side of the power line. The current in the power line conductors 461 and 463 is controlled in the usual manner by a line switch 464.

The switches C-1 to M-1 are arranged in 30 closely adjacent relationship on a supporting frame 470 of the controller 459, see Fig. 37. The several switches C-1 to M-1 are of identical construction comprising a pair of resilient arms 471 and 472 mounted in spaced relationship at one end on opposite sides of an insulating block 473. The arms 471 and 472 and the block 473 are secured to the supporting frame 470 by means of screws 474 projecting through insulating bushings 475, see Figs. 36 and 38. At their outer free ends the arms 471 and 472 of each switch C-1 to M-1 mount opposed contacts 476 and 477 and the arm 471 carries a follower block 478 on its opposite side adapted for engagement with its respective operating cam. As illustrated in Fig. 36, the switch arms 471 and 472 have leaf-springs 479 and 480 overlying one side thereof and the arm 472 has a backing blade 481 overlying the side opposite from the leaf-spring blade 480. The backing blade 481 constitutes a bus-bar for connecting all the arms 472 of the series of switches C-1 to M-1 to one side 461 of the power line through the conductor 460. The arm 471 of each switch C-1 to M-1 projects beyond the insulating block 473 and is angularly bent to provide a terminal for connection with an individual conductor 485 leading to its respective solenoid.

The series of cams C-2 to M-2 of the controller 459 are mounted fast on a shaft 490 with each cam alined with its respective switch C-1 to M-1 to adapt its periphery to engage the bearing block 478 on the switch-arm 471, see Figs. 34 and 36. The several cams C-2 to M-2 are of similar form, each comprising a generally circular disk 491 and a laterally-projecting hub 492 for properly spacing the cams from each

other. The cam-disks 491 have lobes of varying length on their peripheries for flexing the arms 471 of the switches C-1 to M-1 toward the arms 472 to engage the contacts 476 and 477. The cams C-2 to M-2 are fixed to the shaft 490 by means of set-screws or equivalent means with their lobes arranged in a predetermined angular relationship to cause the series of switches to be closed in predetermined timed sequence during one complete revolution of the controller shaft 490.

Usually, the cams C-2 to L-2 are adjusted in angular relation to each other and secured permanently in position on the controller shaft 490 while the cam M-2 is preferably adapted for independent adjustment. The cam M-2 controls the retraction of the bobbin-transferring cradle 376 to bobbin-receiving position and the release of the yarn-retriever 170 for regulating the time interval during which the bunch X is wound on the empty bobbin. Therefore, it is desirable that the time of operation of these elements be regulated in accordance with different conditions of winding such as changes in the size of yarn and type of bobbins to be wound. For this purpose the cam M-2 is adapted for adjustment by means now described. A collar 494 fast on the control shaft 490 located adjacent the cam L-2 is formed with serrations or teeth 495 on its side, see Figs. 34 and 37. The cam M-2 is mounted fast on the inner end of a sleeve 496 slidable longitudinally on the control shaft 490 and has a series of teeth 497 for cooperation with the teeth 495 on the clutch-collar 494. The cam M-2 is normally held with its teeth 497 engaged with the teeth 495 on the clutch-collar 494 by means of a spring 498 acting between the hub of the cam and a bearing 499 on the frame 470. A calibrated knob 500 at the outer end of the sleeve 496 provides for the retraction of the cam M-2 against the action of the spring 498 to disengage the clutch-teeth 497 and 495 and permit angular adjustment of the cam with respect to the hub 494. A pointer 501 on the bearing 499 cooperates with the calibrated knob 500 to indicate the setting of the cam M-2 and thereby the number of turns of yarn in the bunch to be wound.

The controller shaft 490 is rotatably mounted 50 in a bearing 506 and the bearing 499, previously mentioned, at the upper end of arms projecting from the controller-supporting frame 470. The controller shaft 490 is held against longitudinal movement by means of a collar 508 and the hub 55 of a worm-gear 510 which abut the opposite sides of the bearing 506. The controller shaft 490 is driven from the drive shaft 6 through reduction gearing comprising the worm-wheel 510 at the outer end of the shaft 490 which meshes with a worm 511 mounted on a transversely extending shaft 512, see Figs. 36 and 37. The shaft 512 is journaled in bearings 513 and 514 carried by the controller-supporting frame 470 and mounts a spur gear 515 fast thereon. The gear 515 on the shaft 512 meshes with an idler gear 516 adapted to be driven by a pinion gear 517. The idler gear 516 is rotatably mounted on a stud 518 projecting from the frame 470 and the pinion 517 is formed as part of a sleeve 519 journaled on a stud 520 projecting from the frame. A helical gear 522 fast on the outer end of the sleeve 519 meshes with a helical gear 523 keyed to one end of a sleeve 524 on the controller drive shaft 6, see Figs. 35 and 36. Splined to the opposite end of the sleeve 524 is a male

clutch element 525 which is slidable on the sleeve to adapt it to cooperate with a female clutch element 526 held fast on the controller drive-shaft 6 by means of a set-screw 527. The male clutch element 525 and the operating means therefor are substantially identical with the clutch elements 152, 153, previously described, for connecting the controller drive shaft 6 to the thread-guide return means. A shifter lever 532 is adapted to be rocked by means of a spring 533 to disconnect the male clutch element 525 from the female clutch element, the spring having one end connected to the lever and its opposite end anchored to the frame 470. The shifter lever 532 is arranged to be actuated by a spring 534 to connect the clutch elements 525 and 526, the spring having one end connected to the lever and its opposite end connected to the plunger 538 of a solenoid 465. Upon energization of the solenoid 465 the shifter lever 532 will be rocked to engage the male clutch element 525 with the female clutch element 526 whereby the controller drive shaft 6 will drive the controller shaft 490 through the gearing described above to cause the cams C—2 to M—2 to operate the switches C—1 to M—1 to energize the several branch circuits C to M in timed sequence.

A switch 467 is provided in the branch circuit C for energizing the solenoid 465 independently of the controller operated switch C—2, see Fig. 40. Referring to Fig. 15, the switch 467 as herein shown is of the push-button type, known as a micro-switch, being adapted to be actuated by the inclined cam edge 536 of a flange 537 depending from the control member 272 on the sizing rod 274, previously referred to in connection with the starting and stopping mechanism. During the longitudinal growth of the bobbin B the thread-guide 45 is advanced along the traverse rod section 46 until its depending tail portion 110 engages the stop collar 275 on the sizing rod 274. This engagement will cause the inclined edge 536 on the flange 537 to actuate the switch 467 to close the circuit. It will be understood that only a very limited movement of the sizing rod 274 is necessary to actuate the switch 467 whereas a considerably greater movement of the sizing rod is necessary to withdraw the ledge 279 from the depending foot 270 of the mechanical stopping means.

An upstanding flange 537 on the control member 272 is adapted to be engaged by the flange 31 on the spindle-cup 25 when the latter is retracted to doff a wound bobbin, see Fig. 15, thereby acting to slide the control member to return the sizing rod 274 to its initial position to release the switch 467. By the time the sizing rod 274 has been returned to first position the controller 459 will have actuated the switch C—1 of the branch circuit C to take over the energization of the solenoid 465 for connecting the controller to its drive shaft 6 whereby the controller will continue to function throughout its complete cycle of operations before coming to rest.

Mode of operation

The winding operation is initially started at each winding unit of the machine by applying an empty bobbin b in position between the spindle-cup 25 on the spindle 10 and the cupped end 38 of the stub-spindle 39. The empty bobbin b may be inserted manually by pressing its butt end against the spindle-cup 25 with the yarn strand y positioned therebetween, the yielding

5 of the spindle-cup against the action of the spring 30, see Fig. 16, allowing the opposite tip end of the bobbin to be placed in the cupped end 38 of the stub-spindle 39. Upon release of the bobbin b the spring 30 will propel the spindle-cup 25 toward the stub-spindle 39 to clamp the bobbin therebetween and fasten the yarn strand y between the bobbin and spindle-cup.

The starting handle 240 is then rocked manually in a counterclockwise direction as viewed in Fig. 9, to thereby rock the rock-shaft 21 connected thereto, see Fig. 2, which acts through the arms 20, 58 and straps 19, 57 to withdraw the levers 15, 53 from engagement with the flanges 14, 52 of the clutches 13, 51. The clutches 13 and 51 will then be actuated by their springs to slide them into engagement with the helical gears 12 and 50 to connect the drive shafts 4 and 5 to the spindle 10 and cam 47. As the starting handle 240 is rocked into operative position the latch-member 243, see Fig. 10, is rocked by the spring 247 to engage its latching shoulder 245 with the latching shoulder 242 on the arm 241 of the handle to retain the operating levers 15 and 53 out of engagement with the flanges 14 and 52 of the clutches 13 and 51 against the action of the springs 22 and 59. The rotation of the spindle 10 is thus started to rotate the bobbin b to wind the yarn strand y thereon 30 while the cam 47, see Fig. 1, operates through the oscillating lever 61 and link 56 to reciprocate the traverse rod sections 46 and 64 and thereby the thread-guide 45 mounted thereon. The yarn y thus will be traversed by the thread-guide longitudinally of the bobbin b to deposit it thereon in crosswound layers. At the beginning of the winding the inner end of the traverse rod section 54 is forced inwardly toward the bobbin b by the engagement of the finger 108 on the thread-guide 45 with the former-bar 88, as represented by dash-lines in Fig. 5. The contact wheel 104 will be thus maintained with its periphery in close association with the barrel of the bobbin to adapt it to contact with the first 45 layers of yarn deposited thereon. It will be noted that the barrel of the bobbin b is tapered slightly so that as the thread-guide 45 makes a rearward stroke toward the butt end of the bobbin the periphery of the contact wheel 104 will make contact with the surface of the yarn on the bobbin and due to the rotation of the latter the wheel will be turned to a slight extent to advance the guide outwardly along the threaded section 64 of the traverse rod. This advance of 50 the thread-guide continues intermittently with the yarn mass building up into conical form as indicated by the dot-and-dash lines in Fig. 5. Then when the threaded section 64 of the traverse bar has been forced outwardly into alignment with the main section 46 of the bar the contact wheel 104 will be engaged by the base end of the conical chase on which the winding is being performed and the advance of the guide will continue to wind the cylindrical body of 55 the bobbin B.

As the thread-guide 45 is advanced during the winding its depending tail-piece 110, see Fig. 15, will eventually engage the collar 275 adjustably mounted on the sizing rod 274 to actuate the latter to initiate the doffing of the wound bobbin B and the donning of an empty bobbin b. Movement of the sizing rod 274 actuates the control member 272 to cause the inclined edge 536 of its depending flange 537 to operate the switch 467, see Fig. 15. Operation of the switch 467

closes the branch circuit C, see Fig. 40, to energize the solenoid 465 to operate the shifter lever 532, see Fig. 35, and the latter acts to engage the clutch elements 525 and 526 to connect the controller drive shaft 6 to drive the controller shaft 490 through the reduction gearing. The rotation of the controller shaft 490 acts first to cause the cam C-2 to close the switch C-1 of the branch circuit C, see Figs. 40 and 41, to take over the energization of the solenoid 465 to maintain the clutch elements 525 and 526 engaged throughout a doffing and donning operation.

Following the energization of the branch circuit C the cam D-2 of the controller 459 closes the switch D-1 to energize the branch circuit D including the winding of the solenoid 219 for operating the yarn-retriever 170. Upon energization of the solenoid 219, see Figs. 4 and 15, the plunger 218, acting through the bell-crank lever 215, 217, link 212, bell-crank lever 207, link 204, lever 194 and slide 177, moves the yarn-retriever 170 rearwardly along the wound bobbin B. The movement of the yarn-retriever 170 from the position illustrated in Fig. 4 to that illustrated in Fig. 15 occurs while the spindle 10 continues to rotate whereby to traverse the yarn strand y rearwardly along the wound bobbin B to produce a back wind indicated at W in Fig. 15. The rearward movement of the yarn-retriever 170 is limited by the engagement of the detent-fingers 227, see Fig. 15, with the plunger 218 of the solenoid 219 to cause the retriever to halt while a few extra turns are wound at the base end of the bobbin B while the latter continues to rotate.

Simultaneously with the energization of the yarn-retriever solenoid 219 the switch E-1 is closed by the cam E-2 of the controller 459 to energize the branch circuit E which includes the winding of the solenoid 117 for opening the tension-device 114 to relieve the tension on the yarn. After the yarn-retriever 170 has been operated to wind the back wind W the switch E-1 is released by the cam E-2 to deenergize the solenoid 117 and the tension-device 114 is automatically closed to again apply tension to the drawing yarn strand. The electrical control of the tension-device is explained in detail in the copending application, Serial No. 265,315, referred to previously.

After the back wind W has been completed the controller cam F-2 closes the switch F-1 of the branch circuit F to energize the latch-trip solenoid 249. Upon energization of the solenoid 249, see Figs 9 and 10, the plunger 250 and push rod 251 connected thereto act to rock the latch-member 243 to release the starting handle 240. Upon release of the starting handle 240 the springs 22 and 59, see Fig. 2, act to rock the operating levers 15 and 53 into engagement with the flanges 14 and 52 of the clutches 13 and 51 to simultaneously disconnect them from the helical gears 12 and 50 to arrest the rotation of the spindle 10 and the reciprocation of the thread-guide 45, the operating levers acting as brakes to stop rotation of the spindle 10 and cam 47 substantially instantaneously. The cam F-2 retains the switch F-1 closed only long enough to permit the parts to operate to arrest rotation of the spindle 10 and reciprocation of the thread-guide 45.

After the winding elements 10 and 45 have come to rest the controller cam G-2 closes the switch G-1 of the branch circuit G which includes the solenoid 308, see Figs. 9 and 18, for retracting the spindle-cup 25. Energization of

the solenoid 308 actuates the plunger 307 and through the link 309 connected to the arm 306 rocks the bell-crank lever 300 to cause the roller 33 on its arm 34 to engage the flange 31 on the spindle-cup 25 to slide the latter toward the left as viewed in Fig. 15. Upon retraction of the spindle-cup 25 the wound bobbin B drops by gravity into the chute 315, see Fig. 29, where it falls onto and is detained by the pivoted gate 317 as illustrated in Figs. 29 and 31. During the descent of the bobbin B the plate 329 of the yarn-trap 328 pivots to permit the bobbin to pass thereby, after which the spring 341 operates to return the plate to horizontal position. During the return movement of the plate 329 the yarn strand y is guided between the shoulder 349 and the edge of the pivoted element 350 of the yarn-trap 328 to carry the strand into position for attachment to the empty bobbin b to be donned, see Fig. 29. During the retraction of the spindle-cup 25 its flange 31 engages the flange 537 of the control member 272 and moves it rearwardly whereby its inclined cam edge 536 releases the switch 467 which moves to open position in readiness for the next doffing operation; it being understood that meantime the controller switch C-1 has been closed to maintain the solenoid 465 energized whereby to continue the drive for the controller operative.

30 Simultaneously with the retraction of the spindle-cup 25 the controller cam H-2 closes the switch H-1 of the branch circuit H to energize the solenoid 229 for withdrawing the detent fingers 227 to release the plunger 218 of the solenoid 219. The solenoid 219 being still energized then acts through the connecting linkage, previously described, to move the yarn-retriever 170 rearwardly as the spindle-cup is retracted from the position illustrated in Fig. 15 to that illustrated in Fig. 18.

After the wound bobbin B has been doffed the controller arm I-2 operates to close the switch I-1 of the branch circuit I to energize the solenoid 161. The solenoid 161 thus is caused to operate the lever 157, see Fig. 35, to shift the male clutch element 152 into engagement with the clutch element 153, whereby to connect the controller drive shaft 6 to rotate the threaded traverse rod section 64. The drive between the threaded traverse rod section 64 and the controller drive shaft 6 comprises the sprocket 120, see Fig. 4, chain 126, sprocket 124, shaft 125, bevel gears 129, 130, shaft 131, see Fig. 9, bevel gears 134, 135, shaft 136, see Fig. 39, helical gears 144, 145 and clutch elements 152 and 153, see Fig. 35. Thus the threaded traverse rod section 64 is rotated within the nut 101 of the thread-guide 45, the nut being frictionally held by the end of the coil spring 105 to cause the thread-guide to be returned to its initial winding position. At the end of the rearward movement of the thread-guide 45 the threaded portion 102 of the nut 101 slides onto the unthreaded portion 86 of the traverse rod section 64 to prevent further rearward movement of the guide. After the thread-guide 45 has been returned to its initial position the cam I-2 releases the switch I-1 to deenergize the circuit I. During the rearward movement of the thread-guide 45 slack occurs in the yarn strand y due to the release of the loop or bight formed therein by the rearward movement of the yarn-retriever 170 in advance of the return of the thread-guide.

After the thread-guide 45 has been returned to its initial position the controller cam J-2 closes

the switch J-1 of the branch circuit J to energize the solenoid 362 for releasing the pivoted gate 317. Upon energization of the solenoid 362 the plunger 363 acts through the push-rod 364, see Figs. 30 and 31, to slide the rod 319 to the position indicated by dash-lines in Fig. 31 to permit the gate to rock by gravity to release the wound bobbin B. Upon its release the wound bobbin B drops by gravity into the container 389 below the chute 315, thereby taking up the slack in the yarn strand y and drawing it taut between the yarn-retriever 170 and yarn-trap 328 to position it across the end of the spindle-cup 25, see Fig. 33. The branch circuit J is deenergized by the cam J-2 operating on the switch J-1 immediately after the empty bobbin b has been donned.

Shortly after the release of the wound bobbin B from the chute 315 the controller cam K-2 closes the switch K-1 of the branch circuit K to energize the solenoid 453, see Figs. 21 and 28, to withdraw the detent-latch 441 from engagement with the latching finger 450 of the cradle 376 against the action of the spring 451. Upon release of the cradle 376 the spring 446, see Figs. 21 and 22, operates through the link 442, bell-crank lever 441, 439, link 440, and second bell-crank lever 438, 435 to rock the cradle from the position illustrated in Fig. 23 to that illustrated in Fig. 25 to position an empty bobbin b in alignment with the spindle-cup 25 and cupped end 38 of the stub-spindle 39. During the movement of the cradle 376 from the position shown in Fig. 24 to that illustrated in Fig. 26 the upper gate 392 is raised by the sliding movement of the pin 432 in the slot 401 and the gate 393 is lowered by the movement of the pin in the slot 409. Thus the bobbins in the magazine 375 are released by the gate 392 and descend into engagement with the gate 393. The gate 392 carries the detent 236 which is thus positioned to be engaged by the slide 171 to hold the yarn-retriever 170 for winding the bunch X.

When the cradle 376 has been moved to the position illustrated in Figs. 25 and 26 the cam G-2 of the controller releases the switch G-1 to open the branch circuit G whereby the solenoid 308 is deenergized. Upon deenergization of the solenoid 308 the spring 30, see Fig. 16, propels the spindle-cup 25 into engagement with the butt end of the empty bobbin b to clamp it between the cup and the cupped end 38 of the stub-spindle 39 with the yarn strand y clamped against the butt end of the bobbin. Thus an empty bobbin b is donned and the yarn strand attached thereto to be wound thereon.

Following the donning of the empty bobbin b the controller cam L-2 closes the switch L-1 of the branch circuit L to energize the solenoid 262 for starting a new winding operation. Upon energization of the solenoid 262 the plunger 261, operating through the link 260, acts to rock the arm 258 of the bell-crank lever 256 in counterclockwise direction as viewed in Fig. 9. The abutment 259 projecting rearwardly from the arm 258 of the bell-crank lever 256 engages the arm 241 of the starting handle 240 and rocks it to starting position where it is latched by the latch-member 243. The rocking movement of the starting handle 240 and rock-shaft 21 effects starting of the rotation of the spindle 10 and cam 47 in the manner as explained previously. Substantially simultaneously with the closing of the switch L-1 a second lobe on the controller cam E-2 again acts to close the switch E-1 to ener-

gize the solenoid 117 to open the tension-device 114 whereby to relieve the tension on the yarn strand y. The branch circuit E remains energized until the winding operation has started, after which the cam E-2 releases the switch E-1 to deenergize the circuit and the tension-device 114 closes to apply tension to the feeding yarn strand. The relief of tension on the yarn strand at the beginning of the winding operation prevents strain and breakage of the strand by the sudden pull as the bobbin is started to rotate. Upon initial rotation of the winding spindle 10 the yarn strand trailing from the wound bobbin B and attached to the empty bobbin b is tensioned in the yarn-trap 328 which causes it to be drawn against the knife 357 in the manner indicated in Fig. 33 to sever the strand.

After the empty bobbin b has been donned the controller cam D-2 releases the switch D-1 to open the branch circuit D whereby the yarn-retriever actuating solenoid 219 is deenergized. Upon deenergization of the solenoid 219 the spring 235 connected to its plunger 218 operates through the connecting linkage, previously described, to cause the yarn-retriever 170 to move forward toward the right as viewed in Fig. 18. During its initial forward movement the yarn-retriever 170 will engage the detent 236, see Fig. 19, which projects forwardly from the gate 392 whereby it will be held in the position illustrated in Fig. 19 for winding the bunch X on the bobbin b. Due to the detention of the yarn-retriever 170 in this position its inclined edge 172 and crotch 174 will act to restrict the traverse of the yarn strand by the thread-guide 45 to wind a predetermined number of coils on the bobbin b to form the bunch X, as shown in Figs. 19 and 20.

After the bunch X has been completed the controller cam M-2 operates the switch M-1 of the branch circuit M to energize the solenoid 445 for returning the cradle 376 to bobbin-receiving position, see Fig. 22. Upon energization of the solenoid 445 the plunger 444 acting through the connecting linkage rocks the cradle 376 from the position illustrated in Fig. 26 to that illustrated in Fig. 24. During the return movement of the cradle 376 the end of the latching shoulder 450, see Fig. 28, passes across the beveled end of the detent 447 which is thereafter propelled upwardly by the spring 451 to retain the cradle in its bobbin-receiving position. Also during the return movement of the cradle 376 the gate 393 is raised to permit the lowermost bobbin in the magazine 375 to enter the cradle to be gripped by the bobbin-grippers 413 and 414. At the same time the gate 392 is lowered to engage it with the next to the lowermost bobbin b in the magazine to prevent the rest of the bobbins from feeding. The cam M-2 retains the switch M-1 closed only long enough to permit the cradle 376 to be returned to bobbin-receiving position. As the gate 392 is lowered to hold the bobbins in the magazine the detent 236 projecting therefrom, see Fig. 19, is withdrawn to release the yarn-retriever 170 and the latter is returned to the position illustrated in Fig. 4 by action of the spring 235. Upon the release of the yarn-retriever 170 and its return to first position the thread-guide 45 will traverse the yarn strand y to the full extent while advancing outwardly along the traverse rod section 64 to distribute the yarn in overlapping layers which form a cylindrical bobbin B having a conical end.

After a doffing and donning operation has been completed the controller cam C-2 releases the switch C-1 to open the branch circuit C and de-energize the solenoid 465. The spring 533, see Fig. 35, operating on the shifter lever 532 will then disengage the male clutch element 525 from the female clutch element 526 to disconnect the controller shaft 490 from the drive shaft 6. It will be understood that the machine continues to operate in the manner explained to wind bobbins and upon the completion of each to automatically doff the wound bobbin B, don an empty bobbin b and start a new winding operation.

Upon failure of the control member 272 to operate the switch 467 or if, for any reason, the electric control means fails to operate the stopping mechanism, continued movement of the sizing rod 274 by the depending tail-piece 110 on the thread-guide 45 will withdraw the ledge 279 from the depending foot 270 of the control arm 267, see Figs. 13 and 16, so that the spring 273 will rock the arm to the position indicated by dash-lines in Fig. 11. The bunter 276 on the traverse rod section 46 will then engage the control arm 267, see Fig. 11, to rock the rock-shaft 244 and latch-member 243 mounted thereon, see Fig. 10. The latch-member 243 thus will release the starting handle 240 to arrest the rotation of the spindle 10 and cam 47 without operating the doffing and donning mechanism. In this condition it will be indicated to the operator of the machine that some part of the automatic doffing and donning means is not functioning properly. Also upon breakage of the yarn strand or exhaustion of the yarn supply the drop-wire 116 will be released and due to the weight of its tail portion 286 the loop 288 at its end will fall to the position illustrated in Fig. 12 between the bunter 276 and operating arm 267. Rearward movement of the bunter 276 will then act on the loop 288 to rock the arm 267 and thereby the rock-shaft 244 and control member 243 mounted thereon whereby to release the starting handle 240 and arrest the operation of the machine without initiating the operation of the doffing and donning mechanism.

It will be observed from the foregoing specification that the present invention provides an automatic winding machine requiring no attention except to replenish the yarn supplies and refill the magazine with empty bobbins. It will also be observed that the operative elements of the machine are controlled in timed sequence by a single controller or multiple switch for energizing the various operating solenoids arranged in parallel branch circuits.

While a preferred form of the invention is herein illustrated and described it will be understood that modifications may be made in the structure and arrangement of its parts without departing from the spirit or scope of the invention. For example, the various circuits may be energized in different timed sequence from that herein described; the machine may be adapted for winding other types of yarn packages; and the electromagnets may be of any suitable type, such as an ironclad solenoid, the plunger type electromagnet herein shown, or an electromagnet having an external armature. Therefore, without limiting ourselves in this respect, we claim:

1. In an automatic winding machine, a winding spindle for mounting a yarn-carrier, means for doffing a wound carrier and donning an empty carrier, a controller for controlling the oper-

ation of the doffing and donning means in timed sequence, a drive shaft, means for connecting the controller to the drive shaft, an electromagnet for operating the last-named means, an electric circuit for the electromagnet, and a switch in said circuit operative upon completion of the winding on the carrier to energize the electromagnet.

2. In an automatic winding machine, a winding spindle for mounting a yarn-carrier, means for doffing a wound carrier and donning an empty carrier, a controller for controlling the operation of the doffing and donning means in timed sequence, a drive shaft, a clutch for connecting the controller to the drive shaft, an electromagnet for operating the clutch, a circuit for the electromagnet, a switch in said circuit operative upon completion of the winding on the carrier to initially energize the electromagnet, a second switch in the circuit controlled by the controller to energize the electromagnet, and means for opening the first-mentioned switch.

3. In an automatic winding machine, a winding spindle for mounting a yarn-carrier, means for doffing a wound carrier and donning an empty carrier, electromagnets for operating the doffing and donning means, electric circuits for the electromagnets, switches in said circuits, a controller for actuating the switches to energize the electromagnets in timed sequence, a drive shaft, and means operative upon completion of the winding on the yarn-carrier for connecting the controller to the drive shaft.

4. In an automatic winding machine, a winding spindle for mounting a yarn-carrier, means for doffing a wound yarn-carrier and donning an empty carrier, electromagnets for operating the doffing and donning means, an electric circuit for each electromagnet, a switch in each circuit, a controller having a series of cams for closing the switches of the circuits in timed sequence, a drive shaft, and means operative upon completion of the winding on the yarn-carrier for connecting the controller to its drive shaft.

5. In an automatic winding machine, a winding spindle for mounting a yarn-carrier, said spindle being movable longitudinally to doff a wound yarn-carrier, an electromagnet for moving the spindle, a magazine for holding a supply of empty yarn-carriers, means for transferring an empty yarn-carrier from the magazine to the spindle, an electromagnet for initiating the operation of the transferring means, electric circuits for the electromagnets, switches in said circuits for controlling the energization of the electromagnets, a controller having cams for closing the switches in timed sequence, a drive shaft, and means controlled by the growth of the winding on the yarn-carrier for connecting the controller to the drive shaft.

6. In an automatic winding machine, a winding spindle for mounting a yarn-carrier, means for doffing a wound carrier and donning an empty carrier, electromagnets for operating the doffing and donning means, a yarn-retriever for guiding the yarn rearwardly along the wound carrier to form a back wind thereon, an electromagnet for operating the yarn-retriever, electric circuits for the electromagnets, switches in said circuits for controlling the energization of the electromagnets, a controller having a series of cams for closing the switches of the circuits in timed sequence, a drive shaft, and means operative upon completion of the winding on the

yarn-carrier for connecting the controller to the drive shaft.

7. In an automatic winding machine, a winding spindle for mounting a yarn-carrier, means for doffing a wound carrier and donning an empty carrier, electromagnets for operating the doffing and donning means, a yarn-retriever for moving the yarn strand to a position to be clamped to an empty carrier, an electromagnet for operating the yarn-retriever, electric circuits for the electromagnets, switches in said circuits for controlling the energization of the electromagnets, a controller having a series of cams for closing the switches of the electromagnet circuits in timed sequence, a drive shaft, and means operative upon completion of the winding on the carrier for connecting the controller to the drive shaft.

8. In an automatic winding machine, a winding spindle for mounting a yarn-carrier, means for doffing a wound carrier and donning an empty carrier, electromagnets for operating the doffing and donning means, a yarn-retriever for positioning the yarn to wind a bunch on the carrier, an electromagnet for operating the yarn-retriever, electric circuits for the electromagnets, switches in said circuits for controlling the energization of the electromagnets, a controller having a series of cams for closing the switches of the electromagnet circuits in timed sequence, a drive shaft, and means operative upon completion of the winding on the yarn-carrier for connecting the controller to the drive shaft.

9. In an automatic winding machine, a winding spindle for mounting a yarn-carrier, means for doffing a wound carrier and donning an empty carrier, a yarn-retriever for positioning the yarn for attachment to an empty carrier and thereafter positioning the yarn for winding a bunch on the carrier, electromagnets for operating the doffing and donning means and yarn-retriever, electric circuits for said electromagnets, switches in said circuits for controlling the energization of the electromagnets, a controller having a series of cams for operating the switches in timed sequence, a drive shaft, and means operative upon completion of the winding on the carrier for connecting the controller to the drive shaft.

10. In an automatic winding machine, means for rotating a yarn-carrier, a thread-guide, means for relatively traversing the yarn-carrier and thread-guide, means for doffing a wound carrier, a yarn-retriever for positioning the yarn strand for attachment to an empty carrier, means for donning an empty carrier, electromagnets for operating the doffing means, yarn-retriever and donning means, electric circuits for the electromagnets, switches in said circuits for controlling the energization of the electromagnets, a controller for operating the switches in timed sequence, and means for operating the controller.

11. In an automatic winding machine, means for rotating a yarn-carrier, a thread-guide for traversing a yarn strand on the carrier, means for advancing the thread-guide along the carrier during the winding, means for doffing a wound carrier, means for returning the thread-guide to initial winding position, a yarn-retriever for positioning the yarn strand to adapt it to be attached to an empty carrier, means for donning an empty carrier, electromagnets for operating the doffing means, thread-guide return means, yarn-retriever and donning means, elec-

tric circuits for said electromagnets, switches in the circuits for controlling the energization of the electromagnets, a controller having a series of cams for operating the switches in timed sequence, and means operative upon completion of the winding on the carrier for operating the controller.

12. In an automatic winding machine, means for rotating a yarn-carrier, a thread-guide for traversing a yarn strand on the carrier, means for advancing the thread-guide along the carrier during the winding, a yarn-retriever for engaging the yarn strand to traverse it rearwardly on the wound carrier and position it to be attached to an empty carrier, means for doffing a wound carrier, means for returning the thread-guide to initial winding position, means for donning an empty carrier, electromagnets for initiating the operation of the yarn-retriever, doffing means, thread-guide return means and donning means, electric circuits for said electromagnets, switches in said circuits for controlling the energization of the electromagnets, a controller having a series of cams for operating the switches in timed sequence, and means operative upon completion of the winding on a carrier for operating the controller.

13. In an automatic winding machine, means for rotating a yarn-carrier, a thread-guide, means for relatively traversing the yarn-carrier and thread-guide, means for relatively advancing the thread-guide along the yarn-carrier during winding, a yarn-retriever for positioning the yarn strand to adapt it to be attached to an empty carrier, means for doffing a wound carrier, means for returning the thread-guide to initial winding position, means for donning an empty carrier, electromagnets for operating the yarn-retriever, doffing means, thread-guide return means and donning means, electric circuits for the electromagnets, said electric circuits having switches for controlling the energization of the electromagnets, a controller having a series of cams for operating the switches in timed sequence, a drive shaft, a clutch for connecting the controller to be driven from the drive shaft, and means controlled upon completion of the winding on the carrier for operating the clutch.

14. In a winding machine, means for rotating a yarn-carrier, a screw-shaft arranged in spaced relation to the yarn-carrier, a thread-guide on the screw-shaft, means for relatively traversing the yarn-carrier and thread-guide, means for advancing the thread-guide along the screw-shaft during winding, and means for rotating the screw-shaft to return the thread-guide from advance position to initial winding position upon completion of a winding operation.

15. In a winding machine, a winding spindle for rotating a yarn-carrier, means for rotating the spindle, a screw-shaft arranged in spaced relation to the yarn-carrier, a thread-guide on the screw-shaft, means for relatively traversing the yarn-carrier and thread-guide, said thread-guide having a contact wheel in meshing engagement with the screw-shaft and adapted to contact with the yarn wound on the yarn-carrier to advance the thread-guide longitudinally thereof, and means for rotating the screw-shaft to return the thread-guide to its initial winding position after a winding operation.

16. In a winding machine, a winding spindle for rotating a yarn-carrier, means for rotating the spindle, a screw-threaded traverse rod reciprocable longitudinally of the yarn-carrier, a

thread-guide on the traverse rod, said thread-guide having a contact wheel in meshing engagement with the threads of the traverse rod and engageable with the yarn wound on the carrier for advancing the thread-guide longitudinally thereof, and means for rotating the traverse rod to return the thread-guide to its initial winding position after a winding operation.

17. In a winding machine, a winding spindle for mounting a yarn-carrier, means for rotating the spindle, a screw-threaded traverse rod mounted for reciprocation and rotation, means for reciprocating the traverse rod, a thread-guide on the traverse rod, a contact wheel carried by the thread-guide in meshing engagement with the screw-threads on the traverse rod, said contact wheel being adapted to engage the yarn wound on the carrier to advance the thread-guide longitudinally thereof, and means for rotating the traverse rod to return the thread-guide to its initial winding position after a winding operation.

18. In a winding machine, a rotary winding spindle, a screw-shaft, a thread-guide on the screw-shaft, means for relatively traversing the spindle and thread-guide, means for advancing the thread-guide along the screw-shaft during the winding, a drive shaft, and means for connecting the drive shaft to rotate the screw-shaft to return the thread-guide from its advanced position to its initial winding position after a winding operation.

19. In an automatic winding machine, a rotary winding spindle, a screw-shaft arranged in spaced relation to the winding spindle and having helical threads on its periphery, a thread-guide on the screw-shaft, said thread-guide being in continuous engagement with the threads of the screw-shaft, means for relatively traversing the spindle and thread-guide, means for advancing the thread-guide along the screw-shaft during the winding, a drive shaft, and means operative upon completion of the winding for connecting the drive shaft to rotate the screw-shaft whereby to return the thread-guide to its initial winding position.

20. In an automatic winding machine, a winding spindle for mounting a yarn-carrier, a screw-shaft arranged in spaced relation to the yarn-carrier, a thread-guide on the screw-shaft, means for relatively traversing the spindle and screw-shaft, a contact wheel carried by the thread-guide in meshing engagement with the screw-shaft and adapted to contact with the yarn wound on the carrier to advance the thread-guide therewith, a drive shaft, and means operative upon completion of the winding on the carrier for connecting the drive shaft to rotate the screw-shaft whereby to return the thread-guide to its initial winding position.

21. In an automatic winding machine, a winding spindle for mounting a yarn-carrier, a screw-threaded traverse rod adjacent the spindle, a thread-guide on the traverse rod, a contact wheel carried by the thread-guide for engagement with the yarn wound on the carrier and cooperating with the screw-threads for advancing the thread-guide along the traverse rod, during winding, a drive shaft, a clutch for connecting the drive shaft to rotate the traverse rod, and means operative upon completion of the winding on the carrier for actuating the clutch to connect the drive shaft to rotate the traverse rod to return the thread-guide to its initial winding position.

22. In an automatic winding machine, a wind-

ing spindle for mounting a yarn-carrier, a screw-threaded traverse rod adjacent the spindle, a thread-guide on the traverse rod, a contact wheel carried by the thread-guide in meshing engagement with the threads on the traverse rod, said contact wheel being engageable with the yarn wound on the carrier for advancing the thread-guide longitudinally thereof during the winding, a drive shaft, a clutch for connecting the drive shaft to rotate the traverse rod to return the thread-guide to its initial position, an electromagnet for operating the clutch, and means for energizing the electromagnet.

23. In an automatic winding machine, means for rotating a yarn-carrier, a screw-shaft arranged in spaced relation to the yarn-carrier, a thread-guide having means in meshing engagement with the screw-shaft, means for relatively traversing the yarn-carrier and screw-shaft, means for progressively advancing the thread-guide along the screw-shaft during winding, means for doffing a wound carrier and donning an empty carrier, means for rotating the screw-shaft to return the thread-guide to initial winding position, and means operative upon completion of the winding on the yarn-carrier to operate the doffing and donning means and the thread-guide return means.

24. In an automatic winding machine, a winding spindle for mounting a yarn-carrier, a screw-threaded traverse rod, a thread-guide having means in meshing engagement with the screw-threads on the traverse rod, means for reciprocating the traverse rod, means engageable with the yarn wound on the yarn-carrier to advance the thread-guide along the traverse rod, means for doffing a wound carrier from the spindle and donning an empty carrier, a drive shaft, means for connecting the drive shaft to rotate the traverse rod to return the thread-guide to initial winding position, and means operative upon completion of the winding on the carrier to actuate the doffing and donning means and connect the drive shaft to rotate the traverse rod.

25. In an automatic winding machine, a winding spindle for mounting a yarn-carrier, a screw-threaded traverse rod, a thread-guide having means in meshing engagement with the screw-threads on the traverse rod, means for reciprocating the traverse rod, means carried by the thread-guide and adapted to contact the yarn wound on the yarn-carrier to advance the thread-guide during the winding, means for doffing a wound carrier and donning an empty carrier, a drive shaft, a clutch for connecting the drive shaft to rotate the traverse rod to return the thread-guide to its initial winding position, electromagnets for operating the doffing and donning means and the clutch, electric circuits for the electromagnets, and means operative upon completion of the winding on the carrier to close the circuits to energize the electromagnets in timed sequence.

26. In an automatic winding machine, a winding spindle for mounting a yarn-carrier, a thread-guide for traversing a yarn strand on the yarn-carrier, means for progressively advancing the thread-guide along the yarn-carrier during the winding, means for returning the thread-guide to initial winding position, means for doffing a wound carrier and donning an empty carrier, electromagnets for operating the thread-guide returning means and the doffing and donning means, electric circuits for the electromagnets, a series of switches for controlling the electric circuits to energize the electromagnets, a controller

having a series of cams for closing the switches in timed sequence, means for operating the controller, and means actuated upon completion of the winding on the yarn-carrier to connect the controller to its operating means.

27. In an automatic winding machine, means for rotating a yarn-carrier, a thread-guide, means for relatively traversing the yarn-carrier and thread-guide to wind a package, means for advancing the thread-guide progressively along the yarn-carrier during the winding, stopping means for arresting the rotation of the yarn-carrier, and means operated independently of the thread-guide to engage the yarn strand prior to the operation of the stopping means whereby to traverse the yarn rearwardly on the package to form a back wind.

28. In an automatic winding machine, means for rotating a yarn-carrier, a thread-guide, means for relatively traversing the yarn-carrier and thread-guide to wind a package, means for advancing the thread-guide progressively along the yarn-carrier during the winding, an element operated independently of the thread-guide to traverse the yarn rearwardly along the package to form a back wind, stopping means for arresting the rotation of the yarn-carrier, and means for controlling the operation of the back-winding element and stopping means in timed sequence.

29. In an automatic winding machine, means for rotating a yarn-carrier, a thread-guide, means for relatively traversing the yarn-carrier and thread-guide, means for advancing the thread-guide progressively along the yarn-carrier during the winding, a retractable element operated independently of the thread-guide for traversing the yarn rearwardly of the wound yarn-carrier to form a back wind thereon, stopping means, means for controlling the operation of the retractable element and stopping means in timed sequence, and means actuated by the growth of the winding on the yarn-carrier for initiating the operation of the control means.

30. In an automatic winding machine, means for rotating a yarn-carrier, a thread-guide, means for relatively traversing the yarn-carrier and thread-guide, means for advancing the thread-guide along the yarn-carrier during the winding, stopping means for arresting the rotation of the yarn-carrier, means for doffing a wound carrier and donning an empty carrier, and a yarn-retriever for engaging the yarn strand prior to the operation of the stopping means, and means to operate the yarn-retriever to traverse the yarn rearwardly on the wound yarn-carrier to form a back wind and after the doffing of the wound carrier to position the yarn strand to adapt it to be attached to the empty carrier.

31. In an automatic winding machine, means for rotating a yarn-carrier, a thread-guide, means for relatively traversing the yarn-carrier and thread-guide, means for advancing the thread-guide along the yarn-carrier during the winding, means for doffing a wound carrier and donning an empty carrier, a yarn-retriever operative to traverse the yarn rearwardly of the wound yarn-carrier to form a back wind thereon and after the doffing of the wound carrier to position the yarn strand to adapt it to be attached to the empty carrier, and means for operating the yarn-retriever to cause it to move rearwardly to one position and thereafter to move rearwardly to another position.

32. In an automatic winding machine, a winding spindle for mounting a yarn-carrier, a

5 thread-guide, means for relatively traversing the spindle and thread-guide, means for advancing the thread-guide along the yarn-carrier during the winding, a yarn-retriever for engaging the yarn strand to traverse it rearwardly of the wound yarn-carrier to form a back wind thereon, means for retracting the spindle to doff a wound carrier, means for donning an empty carrier, and means for operating the yarn-retriever to cause it to move rearwardly with the spindle as the latter is retracted to position the yarn strand to be clamped between the spindle and the empty carrier.

10 33. In an automatic winding machine, a winding spindle for mounting a yarn-carrier, a thread-guide, means for relatively traversing the spindle and thread-guide, means for advancing the thread-guide along the yarn-carrier during the winding, a yarn-retriever for engaging the yarn strand, means to operate the yarn-retriever to traverse the yarn strand rearwardly of the wound yarn-carrier during the continued rotation of the latter, a detent for limiting the rearward movement of the yarn-retriever, means for simultaneously retracting the spindle to doff a wound carrier and withdrawing the detent to permit the yarn-retriever to move rearwardly with the spindle to position the yarn strand across the end thereof, and means for donning an empty yarn-carrier.

15 34. In an automatic winding machine, a winding spindle for mounting a yarn-carrier, a thread-guide, means for relatively traversing the spindle and thread-guide, means for advancing the thread-guide along the yarn-carrier during the winding, a yarn-retriever operative to engage the yarn strand and traverse it rearwardly on the yarn-carrier to produce a back wind thereon, a detent for limiting the rearward movement of the yarn-retriever, means to retract the spindle to doff a wound yarn-carrier, electromagnets for operating the yarn-retriever and the spindle-retracting means, electric circuits for the electromagnets, a controller for the electric circuits adapted to energize the electromagnets in timed sequence to first operate the yarn-retriever and thereafter to simultaneously retract the spindle and withdraw the detent whereby the spindle and yarn-retriever move rearwardly as a unit, and means for donning an empty carrier.

20 35. In an automatic winding machine, means for rotating a yarn-carrier, a thread-guide, means for relatively reciprocating the yarn-carrier and thread-guide to traverse yarn on the carrier, means for doffing a wound carrier and donning an empty carrier, a yarn-retriever for engaging the yarn strand between the thread-guide and empty carrier to retain the strand at the beginning of a winding operation, said yarn-retriever being so shaped as to restrict the extent of traverse of the yarn strand by the thread-guide to cause a bunch to be wound on the carrier, and means for moving the yarn-retriever longitudinally of the yarn-carrier to inoperative position.

25 36. In an automatic winding machine, means for rotating a yarn-carrier, a thread-guide, means for relatively reciprocating the yarn-carrier and thread-guide to traverse yarn on the carrier, means for doffing a wound carrier and donning an empty carrier, a yarn-retriever for positioning the yarn strand to adapt it to be attached to the empty carrier, means to operate the yarn-retriever to engage the yarn strand

between the thread-guide and empty carrier and restrict its traverse to wind a bunch on the carrier, and means for moving the yarn-retriever to inoperative position upon completion of the bunch winding.

37. In an automatic winding machine, means for rotating a yarn-carrier, a thread-guide, means for relatively reciprocating the yarn-carrier and thread-guide to traverse yarn on the yarn-carrier, means for advancing the thread-guide along the yarn-carrier during the winding, a yarn-retriever, means to operate the yarn-retriever to traverse the yarn strand rearwardly of the wound carrier to form a back wind thereon, means for donning an empty carrier, and means for positioning the yarn-retriever after the donning of an empty carrier to restrict the traverse of the yarn strand to wind a bunch adjacent the rearward end of the carrier.

38. In an automatic winding machine, means for rotating a yarn-carrier, a thread-guide, means for relatively reciprocating the yarn-carrier and thread-guide to traverse the yarn on the yarn-carrier, means for advancing the thread-guide along the yarn-carrier during the winding, a yarn-retriever for engaging the yarn strand being wound, means for doffing a wound yarn-carrier and donning an empty carrier, and means for operating the yarn-retriever to cause it to traverse the yarn rearwardly of the wound yarn-carrier to form a back wind thereon, position the yarn strand to adapt it to be attached to the empty carrier, and thereafter restrict the traverse of the strand at the beginning of a winding operation to wind a bunch adjacent the rearward end of the empty carrier.

39. In an automatic winding machine, means for rotating a yarn-carrier, a reciprocating thread-guide for traversing the yarn on the yarn-carrier, means for advancing the thread-guide along the yarn-carrier during the winding, a yarn-retriever normally positioned adjacent the outer end of the carrier, means for operating the yarn-retriever to traverse the yarn rearwardly of the wound carrier to form a back wind thereon, means for doffing a wound carrier and donning an empty carrier, means for operating the yarn-retriever to position the yarn strand to adapt it to be attached to the empty carrier, and means operative after the donning of an empty carrier for positioning the yarn-retriever to restrict the traverse of the strand to wind a bunch adjacent the rearward end of the empty carrier.

40. In an automatic winding machine, means for rotating a yarn-carrier, a reciprocating thread-guide for traversing the yarn on the yarn-carrier, means for advancing the thread-guide along the yarn-carrier during the winding, a yarn-retriever having a predetermined extent of movement longitudinally of the yarn-carrier, means for operating the yarn-retriever to traverse the yarn strand rearwardly of the yarn-carrier to form a back wind thereon, a detent for limiting the rearward movement of the yarn-retriever, means for doffing a wound carrier and donning an empty carrier, means for withdrawing the detent to adapt the yarn-retriever to continue its movement rearwardly to locate the yarn strand in position to be attached to the empty carrier, means for moving the yarn-retriever forwardly, a second detent for limiting the forward movement of the yarn-retriever to cause it to retain the yarn strand in position to wind a bunch, and means for withdrawing the second detent to permit the yarn-retriever to be returned to its inoperative position.

41. In an automatic winding machine, means for rotating a yarn-carrier, a thread-guide for traversing the yarn on the yarn-carrier, means for relatively reciprocating the yarn-carrier and thread-guide, means for advancing the thread-guide along the yarn-carrier during the winding, means for doffing a wound carrier and donning an empty carrier, a yarn-retriever for engaging the yarn strand to restrict its traverse to wind a bunch on the yarn-carrier, electromagnet-operated means for controlling the period of engagement of the yarn by said yarn-retriever, an electric circuit for said electromagnet, and adjustable timing means for controlling the energization of the electromagnet whereby to regulate the size of the bunch for particular conditions.

42. In an automatic winding machine, means for rotating a yarn-carrier, a thread-guide for traversing a yarn strand on the carrier, means for relatively reciprocating the yarn-carrier and thread-guide, means for doffing a wound carrier, means for donning an empty carrier, a movable member for receiving and positioning an empty carrier to be donned, a detent for engaging said member to retain it in inoperative position, means for withdrawing the detent to release said member, means for moving the member into position to don an empty carrier, and means for moving the member to inoperative position to be engaged by the detent.

43. In an automatic winding machine, means for rotating a yarn-carrier, a thread-guide for traversing a yarn strand on the carrier, means for relatively reciprocating the yarn-carrier and thread-guide, a magazine for holding a supply of empty carriers, means for doffing a wound carrier, means for donning an empty carrier, a movable member for receiving and transferring an empty carrier from the magazine into position to be donned, a detent for engaging said member to retain it in inoperative position, means for withdrawing the detent to release the member, means for moving the member into operative position to don an empty carrier, and means for moving the member to inoperative position to be engaged by the detent.

44. In an automatic winding machine, a rotatable spindle for mounting a yarn-carrier to be wound, a thread-guide for traversing a yarn strand on the yarn-carrier, means for relatively reciprocating the yarn-carrier and thread-guide, means for retracting the spindle to doff a wound carrier, means for advancing the spindle to don an empty carrier, a movable member for receiving and positioning an empty carrier to adapt it to be engaged by the spindle, a detent engaging said member to normally hold it in spaced relationship to the spindle, means for withdrawing the detent to release said member, means for moving the member to position an empty carrier to be donned, and means for moving the member to inoperative position to be engaged by the detent.

45. In an automatic winding machine, means for rotating a yarn-carrier, a thread-guide for traversing a yarn strand on the carrier, means for relatively reciprocating the yarn-carrier and thread-guide, means for doffing a wound carrier, means for donning an empty carrier, a movable member for positioning an empty carrier to be donned, a detent for retaining said member in inoperative position, an electromagnet for withdrawing the detent, resilient means for moving the member to place an empty carrier into position for donning, an electromagnet for moving

the member to inoperative position to be engaged by the detent, electric circuits for said electromagnets, and means for controlling said circuits to energize the electromagnets in timed sequence.

46. In an automatic winding machine, a rotatable spindle for mounting a yarn-carrier, a thread-guide for traversing a yarn strand on the yarn-carrier, means for relatively reciprocating the yarn-carrier and thread-guide, an electromagnet for retracting the spindle to doff a wound carrier, means for moving the spindle to don an empty carrier, a movable member for placing an empty carrier into position to be donned, a detent for retaining said member in inoperative position, an electromagnet for withdrawing the detent, means for moving the member to operative position for donning an empty carrier, an electromagnet for moving the member to inoperative position to be engaged by the detent, electric circuits for said electromagnets, and means for controlling said electric circuits to energize the electromagnets in timed sequence.

47. In an automatic winding machine, a winding spindle for rotating a yarn-carrier, a thread-guide, means for relatively traversing the spindle and thread-guide, means for doffing a wound carrier, a chute for receiving the doffed carrier, a gate in the chute for retaining the wound carrier adjacent the spindle, means for donning an empty carrier, and means for operating the gate to release the wound carrier to tension the yarn strand prior to donning an empty carrier.

48. In an automatic winding machine, a winding spindle for rotating a yarn-carrier, a thread-guide, means for relatively traversing the yarn-carrier and thread-guide, means for advancing the thread-guide during winding, means for doffing the wound carrier, a chute, a gate in the chute for retaining a doffed carrier adjacent the spindle, means for returning the thread-guide to initial position, means for operating the gate after the return of the thread-guide to release the wound carrier to take up the slack in the yarn strand, and means for donning an empty carrier.

49. In an automatic winding machine, a winding spindle for rotating a yarn-carrier, a thread-guide, means for relatively traversing the yarn-carrier and thread-guide, means for advancing the thread-guide along the yarn-carrier during the winding, means for doffing a wound carrier, a chute for receiving the doffed carrier, a rockable gate in the chute for retaining the doffed carrier adjacent the spindle, means for retaining the gate in closed position, means for returning the thread-guide to initial winding position, an electromagnet for actuating the gate-retaining means to release the wound carrier to take up the slack in the yarn strand caused by the return of the thread-guide, and means for donning an empty yarn-carrier.

50. In an automatic winding machine, a retractable spindle for rotating a yarn-carrier, a thread-guide, means for relatively traversing the yarn-carrier and thread-guide, means for advancing the thread-guide along the yarn-carrier during the winding, a yarn-retriever for positioning the yarn strand across the end of the spindle, means for retracting the spindle to doff a wound carrier, means for returning the thread-guide to initial winding position, a chute for receiving the doffed yarn-carrier, a gate in the chute for retaining the doffed yarn-carrier adjacent the

spindle, and a yarn-trap for engaging the yarn strand, said yarn-retriever and yarn-trap acting to position the yarn strand across the end of the spindle, means for actuating the gate to release the wound carrier to take up the slack in the yarn strand caused by the return of the thread-guide whereby to tension the yarn strand between the yarn-retriever and yarn-trap, and means for donning an empty carrier.

51. In an automatic winding machine, a winding spindle for rotating a yarn-carrier, a thread-guide, means for relatively traversing the spindle and thread-guide, means for doffing a wound carrier, a chute for receiving the doffed yarn-carrier, a plate overlying the chute and having a slot therein arranged so that the descent of the wound carrier in the chute guides the yarn strand into the slot, a knife fixedly attached to the plate and extending across the slot, means for donning an empty carrier, and means for starting rotation of the spindle, said slot being so constructed and arranged as to guide the yarn strand against the knife upon initial rotation of the spindle.

52. In an automatic winding machine, means for rotating a yarn-carrier, a thread-guide, means for relatively traversing the yarn-carrier and thread-guide, stopping means for arresting the rotation of the yarn-carrier and the operation of the traversing means, an electromagnet for operating the stopping means, and mechanical means operative by abnormal growth of the winding on the yarn-carrier and acting independently of the electromagnet to actuate the stopping means.

53. In an automatic winding machine, means for rotating a yarn-carrier, a thread-guide, means for relatively traversing the yarn-carrier and thread-guide, stopping means for arresting the rotation of the yarn-carrier and the operation of the traversing means, electrically controlled means for doffing a wound yarn-carrier, donning an empty yarn-carrier and operating the stopping means, and mechanical means automatically operative upon occurrence of abnormal winding conditions for operating the stopping means without operating the donning and doffing means.

54. In an automatic winding machine, means for rotating a yarn-carrier, a thread-guide, means for relatively traversing the yarn-carrier and thread-guide, stopping means for arresting the rotation of the yarn-carrier and the operation of the traversing means, means for doffing a wound carrier and donning an empty carrier, electromagnets for operating the doffing and donning means and stopping means, electric circuits for the electromagnets, a controller for controlling the energization of the electric circuits in timed sequence, and mechanical means operative independently of the electric circuits to operate the stopping means.

55. In an automatic winding machine, means for rotating a yarn-carrier, a thread-guide, means for relatively traversing the yarn-carrier and thread-guide, stopping means for arresting the rotation of the yarn-carrier and the operation of the traversing means, means for doffing a wound yarn-carrier and donning an empty carrier, electromagnets for controlling the operation of the doffing and donning means and the stopping means, electric circuits for the electromagnets, means controlled by the growth of the winding on the yarn-carrier for energizing the electric circuits, and mechanical means operative upon excessive growth of the winding on the yarn-carrier to operate the stopping means independently of the electric circuits.

56. In an automatic winding machine, means for rotating a yarn-carrier, a thread-guide, means for relatively traversing the yarn-carrier and thread-guide, stopping means for arresting the rotation of the yarn-carrier and the operation of the traversing means, electric means for automatically doffing a wound yarn-carrier, donning an empty carrier and operating the stopping means, and mechanical means responsive to excessive growth in the winding on the yarn-carrier or breakage of the yarn strand for operating the stopping means without operating the doffing and donning means.

57. In an automatic winding machine, means for rotating a yarn-carrier, a thread-guide, means for relatively traversing the yarn-carrier and thread-guide, means for starting or stopping the winding operation, said last-named means being normally operative to stop the winding operation, means for latching the starting and stopping means, a latch-trip for releasing the starting and stopping means to arrest the winding operation, electric means for doffing a wound carrier, donning an empty carrier and operating the latch-trip in timed sequence, and mechanical means responsive to excessive growth in the winding on the yarn-carrier or breakage of the yarn strand to operate the latch-trip independently of the electric means to arrest the winding on the yarn-carrier.

58. In an automatic winding machine, means for rotating a yarn-carrier, a thread-guide, means for relatively traversing the yarn-carrier and thread-guide, electromagnet-operated means for arresting operation of the rotating means for the yarn-carrier and the traversing means, means for doffing a wound carrier and donning an empty

carrier, and electromagnet-operated means for initiating operation of the rotating means for the yarn-carrier and the traversing means.

59. In an automatic winding machine, a winding spindle for rotating a yarn-carrier, a thread-guide, means for relatively traversing the yarn-carrier and thread-guide, stopping means for arresting operation of the winding spindle and the traversing means, means for doffing a wound carrier and donning an empty carrier, means for starting operation of the winding spindle and traversing means, electromagnets for operating the stopping and starting means, electric circuits for the electromagnets, switches in the electric circuits, and means for controlling the operation of the switches in timed sequence.

60. In an automatic winding machine, a winding spindle for rotating a yarn-carrier, a thread-guide, means for relatively traversing the yarn-carrier and thread-guide, means for stopping or starting a winding operation, said last named means being normally operative to stop the winding operation, an electromagnet for operating the starting and stopping means to initiate a winding operation, means for latching the starting and stopping means, a latch-trip for releasing the latching means to arrest the winding operation, an electromagnet for operating the latch-trip, means for doffing a wound carrier and donning an empty carrier, electric circuits for the electromagnets, switches in the electric circuits, and a controller for controlling the operation of the switches in timed sequence.
